PROCESS OF AND APPARATUS FOR PRO-
DUCING COVERING MATERIALAlfred B. Walton, Kenmore, N. Y., assignor to
Certain-teed Products Corporation, New York,
N. Y., a corporation of Maryland

Application April 15, 1935, Serial No. 16,329

36 Claims. (Cl. 91—43)

This invention relates to methods of and apparatus for the manufacture of covering materials and more especially to the manufacture of covering materials having portions of the surface thereof contrasting with other portions of the surface thereof to produce design effects or to simulate covering constructions utilizing individual units. The invention particularly relates to the methods of and apparatus for the manufacture of roofing and roofing elements having upon the surface thereof a plurality of areas of contrasting appearance or color.

In the prior art many types of roof covering sheets and of roofing elements have been formed with portions of the surface thereof of contrasting appearance for producing designs or for the purpose of providing sections or areas simulating individual shingles or roofing units of contrasting appearance. Roofing strips formed to simulate a plurality of individual shingles in laterally adjacent arrangement with the laterally adjacent sections of contrasting appearance have been proposed in many forms. In such roofing elements the contrasting appearance has been secured in many cases by the application to the adjacent areas of granular surfacing materials of different colors or of different mixtures of colors in order to obtain different shades. Such prior art covering elements have been made, particularly as roofing elements, by binding upon a sheet or strip of asphalt impregnated roofing felt slate of the desired colors or shades, the bond being effected by a coating of asphalt upon the surface of the felt to which coating the granular slate adheres. The present invention, while not limited in its scope to the application of granular material such as slate to such roofing sheets so coated with asphalt, has particular application in the manufacture of roofing sheets and of roofing elements of this character and for the most part the invention will be described in connection with the manufacture of such roofing sheets and elements.

For the purpose of making roofing strips having thereon shingle simulating sections of contrasting colors heretofore it has been proposed to apply to a continuous sheet of asphalt coated roofing felt granular slate in bands lengthwise of the sheet, the different bands being of different color, and thereafter to cut the sheet transversely thereof into the strips to make roofing elements simulating a plurality of shingles in laterally adjacent arrangement and of contrasting color. In practicing such a method, by suitable means, laterally adjacent streams or showers

of granular material contrasting with each other may be fed toward the sheet as it passes in a direction at right angles to the lateral arrangement of the streams and the bands may be laid closely adjacent upon the sheet. 5

The present invention may utilize such a method of surfacing a roofing sheet to produce roofing strips but in its broad features provides a process of and apparatus for applying upon a sheet of material in the direction of a surface dimension thereof successive masses of differently colored or contrasting granular materials with such control as to lay a mass of a given color or characteristic upon a defined area of the sheet and so that said mass is immediately adjacent 10 and sharply demarcated from the masses laid upon areas of the sheet immediately previous to and following said first mass in the direction of said dimension of the sheet. By means of the apparatus of the invention, the material is so delivered to 15 the sheet and its flow is so controlled as to predetermine the amount of material of a given color to be laid upon the sheet; also so as to determine the rate of delivery of material to the sheet with respect to the rate of movement of the sheet 20 past the point of application of the granular material so that, in consideration of said predetermined amount, the granular material is delivered to a defined area in predetermined relation to adjacent defined areas. Particularly is the flow 25 of the material so controlled that the delivery and laying thereof upon the sheet are sharply cut off at the moment when delivery and laying of the succeeding mass of granular material are started and so that the areas covered by said two 30 masses of granular material are neither separated 35 nor overlapped but are sharply demarcated from each other.

In the normal application of the invention to the manufacture of materials in continuous 40 sheets of substantial length the processes may be carried out and the apparatus may be arranged so as to effect successive cut-offs of one material with the simultaneous starting of the adjacent material while the sheet is moved lengthwise 45 thereof with respect to the devices for applying the granular material to the sheet. By the process of and with the apparatus for carrying out the process of the invention, not only may successive areas lengthwise of the sheet be covered with granular material of contrasting shade or color, each area upon the sheet being sharply demarcated from the other, but the dimension lengthwise of the sheet of these different areas 50 may be controlled or may be adjusted and

changed to suit different conditions of operation. Moreover, the invention may be utilized to produce a covering material having color areas or blocks upon the surface thereof of different dimensions lengthwise of the sheet. In combination with the above referred to methods of the prior art it may produce a sheet having color areas or blocks of dimensions different from adjacent color areas or blocks both lengthwise and transversely of said dimension of the sheet. Covering elements, such as roofing strips, having adjacently arranged sections of different widths and color may be obtained when the sheet having contrasting color areas of different dimension lengthwise of the sheet is cut lengthwise thereof. Strips of different depth, that is, transversely of the long dimension of the strip, may be obtained when such strips are made by applying the granular material in a plurality of streams and are cut transversely of the length of the sheet, successive strips being of contrasting color.

In an elemental application the invention concerns the delivery to a sheet of material, of a given width and moving lengthwise of the sheet, of successive masses of granular material upon areas extending the full width of the sheet and of defined dimension lengthwise of the sheet. Such a width in this simple application may be that of the band produced by one of the parallel streams as utilized in the prior art processes. The areas of different color or of different character may form what above have been called blocks or color areas upon the sheet. The successive color areas upon such a sheet or band are laid contiguous to and consecutive to each other in the direction of the length of the sheet or of the band but with sharp demarcation from each other without substantial overlapping or intermixture of the marginal portions of the different color masses.

One essential feature of the invention is the feeding of the two successive color masses in such a defined path and under such control in said path that, without interposing between two successive differently colored masses any parts of the apparatus utilized, these masses may move forward one following the other in their travel toward the sheet and may be laid upon the sheet without separation of the masses and without intermixture of the granules thereof in the marginal portions of the masses. In other words, the movement of the contiguous masses is so controlled that the sharp demarcation obtained by the initial placement of the two successive color masses, with the line of separation thereof sharply demarking these masses from each other, is maintained when these masses reach and are laid upon the sheet.

Another essential feature of the invention is the control of the feed of the granular material toward the sheet in such a way that the quantity delivered in a given time relation to the movement of the sheet to which the material is being applied is not only correct for the application of a color mass to the desired length of the moving sheet but also so that it may be varied to increase or decrease the dimension lengthwise of the sheet of the area being covered by a color mass. In the simple application referred to above in which a sheet of given width is surfaced with the granular material in a color area extending for the full width of the sheet or of a band upon a sheet the invention provides for the application of each color mass for a length lengthwise of the sheet which may be

predetermined and, moreover, may be varied when desired to obtain color areas of different dimension lengthwise of the sheet.

An important feature of the invention resides in the method of and means for so controlling the feeding of the granular material which is laid upon the sheet that the amount laid upon a given area and the thickness of the layer laid upon said area are controlled and predetermined.

In order to accomplish effective control of the character described, I utilize a slot which may be termed a metering slot, the volume of which is greater than the volume of granular material to be laid upon a given color area upon the sheet. Preferably the volume of the slot exceeds by a substantial amount the volume of the largest mass of granular material to be laid upon the sheet, that is, in the usual case, to be laid upon the longest area lengthwise of the sheet when the granules are laid in a uniform thickness upon the sheet. This volume of the slot conceivably may be sufficient to hold parts of the preceding mass and of the succeeding mass as well as the mass being metered. By thus providing a volume greater than the volume to be laid upon the color area it is possible to deliver into the slot in a manner hereafter to be described the full amount of material of a given color for laying upon a color area.

The feed of this mass of material from the slot toward the sheet is so limited and controlled at the outlet end of the slot that to the inlet end of the slot may be freely delivered the succeeding mass of granular material of different color. The color mass previously delivered into and partly withdrawn therefrom, so that it occupies the lower portion of the slot, is so distributed therein that it presents substantially an even surface upon which may be freely delivered and superimposed the succeeding color mass. If the slot is arranged in a vertical position and has its width, that is, the dimension thereof which is in the direction of the motion of the sheet to which it is to be delivered, sufficiently restricted, then the granular material may be distributed in the slot lengthwise thereof, that is, in the direction transversely of the motion of the sheet and parallel to the surface thereof, so as to present substantially a uniform flat surface of the color mass which is in the lower portion of the slot. The succeeding color mass delivered directly upon the color mass of granules lying in the slot may be sharply demarcated from the lower color mass at the line of separation of the two masses. If now, in the manner to be described, the color mass lying in the lower portion of the slot is withdrawn from the lower outlet area thereof under proper control, the whole mass of material, including the lower color mass and the superimposed mass of granules of contrasting color, will move downward through the slot and the sharp demarcation of one mass from the other may be maintained.

In order properly to control the discharge or withdrawal of the granular material from the slot, in a fundamental conception of the invention I mount the slot above the moving sheet but closely adjacent thereto and with the outlet of the slot in such spaced relation to the surface of the sheet to be covered as to provide what substantially may be designated as an orifice opening in the vertical plane between the lower edge of the slot and the surface of the sheet. While this feature of the invention will be more completely understood from the description to

follow in connection with the drawings, in the arrangement of the structure of the apparatus which forms the slot in relation to the moving sheet, essentially I secure control of the withdrawal of the granular material from the slot not by the area of the slot opening at the lower outlet thereof under the action of gravity upon the granular material falling through the slot, but by the relation of the speed of the moving sheet 5 to the height above the sheet of the slot structure or its equivalent providing substantially an orifice area in the vertical plane, thus determining the amount of material which is caused to pass forward upon the surface of the moving sheet. 10 Stated in another way, in a sense the slot structure provides a scraper or doctor bar which is placed at a predetermined height above the sheet to be covered and thereafter determines the thickness of the material which is to be laid upon the sheet moving immediately beneath. This thickness determines the amount of material withdrawn from the slot and the rate of withdrawal from the slot is determined by the speed of the moving sheet. 15 For reasons which will be more clear from the description to follow, in practice the apparatus of the invention utilizes intermediate between the metering slot and the sheet of material to be covered preferably an apron or belt as a feeder which may be mounted in suitable relation to the metering slot to prevent gravity flow of the granular material from the slot, except as controlled by the motion of the apron or feeder. The depth of material on said feeder is determined, in the manner described above, by the doctor bar or its equivalent which substantially provides a vertical orifice. It will be understood that upon this apron or feeder, as upon the sheet itself, may thus be laid successive masses of differently colored granular materials in amounts predetermined to cover a predetermined area upon the feeder, that is, particularly the predetermined length of its extent in the direction of the motion of the feeder surface. Moreover, it will be understood that the sharp demarcation of the successive masses will be secured and maintained upon a feeder of suitable design so that this feeder may deliver the predetermined masses arranged in predetermined successive order and in predetermined relation to the motion of the sheet 20 so that areas of predetermined extent upon the sheet may be covered with masses of predetermined color and of predetermined thickness and these areas may be sharply demarcated from each other on the sheet. 25

In the elemental application which has been referred to above, it has been assumed that the granules of a single color are supplied over the full width of the sheet or of a band upon the sheet lengthwise of its movement. As has been stated above, the slot in such a case would extend the full width of the sheet or of the band. If an opening through which granular material were delivered under action of gravity were of substantial dimensions in both horizontal directions there would be a tendency for the material at the center of the opening to flow faster than at the walls of the opening and thus delivery of the material would not be uniform throughout the area of the opening, and the top surface of a mass of granules in the slot or opening would not be flat and even. The slot of the invention, however, has width in the direction of motion of the sheet or of the feeder so limited as to prevent substantial differences in flow in different portions of

the areas of the slot. This may be the case even though the slot may be of considerably greater length, that is, in a direction of the dimension of the sheet transversely of the motion of the sheet, than the width thereof in the direction of motion of the sheet. It is, therefore, a feature of the invention to utilize a slot which may be of considerable length but is of such restricted width that a uniform flow therefrom may be produced and a uniform area of substantially flat 10 surface of the material therein may be secured, upon which surface the succeeding color mass of granular material may be superimposed. The height of the slot is such that sufficient volume is provided to hold at least one charge of a color 15 mass fully to cover the color area for the desired length thereof lengthwise of the sheet in addition to a certain portion of a preceding color mass not yet fully withdrawn from the slot. 20

In the elemental embodiment of the invention 25 the slot may be arranged stationary with respect to the moving sheet passing thereunder, the different color masses being successively delivered from the slot on to the sheet. To bring about successive delivery of the color masses to the slot, a magazine, divided into compartments or pockets and containing in the different compartments the different color masses or masses of granules of contrasting appearance, may be moved so that the compartments in succession 30 are positioned over the slot. Each compartment may be provided with an opening or outlet in the bottom thereof so that as a result of moving the magazine the different outlets successively are brought into register with the upper inlet opening of the slot and the different color masses may be delivered to the slot in the order of the compartments in which they lie. While such an elemental form of the invention embodies the fundamental features thereof, in a practical embodiment it may be preferable or necessary to arrange the magazine stationary and to move the structure in which the slot is formed with respect to the openings of the compartments or pockets of the magazine. This relative motion 35 of the slot and the magazine accomplishes as effectively as in the simple embodiment of the invention referred to above the delivery of the different color masses of granular material into the slot in a measured quantity and with sharp 40 demarcation from the granular material previously deposited in the slot. All the other advantages of the slot arrangement also are maintained. 45

In this preferred embodiment, in view of the 50 motion of the structure in which the slot is formed, there also is produced what may be called a differential movement of the structure in which the slot is formed with respect to the sheet or feeder. It will be understood that if the slot is 55 moved continuously in one direction this differential movement may be maintained at a desired constant amount, or with such predetermined variations as may be suitable, so as to effect the laying of the granular material upon 60 the desired length in the direction of movement of the feeder or of the sheet. In the preferred embodiment of the invention, however, in order to simplify the mechanism and the delivery of the materials from storage sources to the magazine and thence to the slot, it has been found to be advantageous to move the slot carrying structure or member with a reciprocating motion beneath the magazine to secure successive opening 65 and closing of the outlets from the compartments 70 75

or pockets of the magazine so as to effect the delivery of the successive contrasting masses of granular material into the slot. When such a reciprocating motion is given to the slot, there is produced when the slot forming member is moved in one direction a differential movement which is different from that produced when the said slot forming member is moved in the opposite direction. It thus becomes necessary to compensate for this difference in differential movement and the means of compensation for this difference in differential motion is a feature of the invention.

In the practical or preferred embodiment this means cooperates with the means which are effective to produce the feeding of the granular material to the slot and the metering of the quantity so fed, to control the feed to the slot and the withdrawal from the slot for delivery to the sheet, to control the amount of material to be laid upon a given length of the sheet for a given width thereof, that is, upon what herein has been called a color area, and to control the motions of the several parts so that the material laid upon one color area of a given length is equal to or in a predetermined relation to that laid upon the succeeding color area or color areas while producing a sharp demarcation of one color area from the adjacent color areas.

In addition to the broad features of the invention, as set forth in the general statement above, the invention includes the method of and means for predetermining the extent of the color area to be surfaced, the method of and means for varying the extent of said color area and of each succeeding color area, the means for varying the adjustment of the various parts to produce color areas of different dimensions lengthwise of the sheet, the application to successive color areas of granular material of different colors or contrasting appearance in such order and arrangement and with such intervals between the repetition of the application of the granular material of the same color or appearance that a substantial variation of the color areas is obtained, and the means for controlling the thickness of the layer on which the granular masses are applied to the sheet. When the sheet is cut into elements such as roofing shingles, not only are the elements completely surfaced with granular material in the desired variety of color areas, but no presorting or rearrangement of the shingles as they are discharged from the roofing machine is necessary in order to insure, when said shingles are laid upon a roof, that the variation of the color effects in the roof assembly may be produced which is desirable and has been the aim of many inventions to accomplish.

The invention now will be more fully explained in connection with the drawings in which

60 Figure 1 is a diagrammatic showing of the slot and magazine arrangement;

Figure 2 is a similar diagrammatic drawing of the magazine in a different relation to the slot;

65 Figure 3 shows, in cross-section, a modified form of the invention;

Figure 4 is an elevation of the apparatus of the invention viewed in the direction of movement of the roofing sheet;

70 Figure 5 is a cross-section on line 5—5 of Figure 4;

Figure 6 is a side elevation of the apparatus of the invention;

75 Figure 7 shows diagrammatically a modified form of the invention; and

Figure 8 shows diagrammatically a sheet of material having color areas thereon.

In Figure 8 is shown diagrammatically a sheet 5 which may have a defined width and may be of indefinite length. Upon the sheet are formed bands longitudinally thereof which may be of different widths in a direction of the width of the sheet or, if desired, may be of equal width. In each of these bands color areas may be formed 10 adjacently arranged in the direction of the length of the sheet, these color areas contrasting with each other. For example, in the band next the lower edge of the sheet 1 as shown in Figure 8, color areas designated by the letter Y, B, G, and R may be those provided by granular material 15 having colors contrasting as are the colors yellow, blue, green and red. It is a feature of the invention that these color areas in such a band shall be sharply demarcated from each other and the apparatus herein described and the method 20 which such apparatus carries out has for its purpose the laying upon a sheet lengthwise thereof, or upon a band lengthwise thereof, successive color areas of contrasting appearance or character which are immediately adjacent each other 25 in said lengthwise direction, each color area being sharply demarcated from its adjacent color areas.

In Figure 8 are shown four such bands upon the sheet 1 extending lengthwise thereof with the color areas in each band arranged similarly to that described in connection with the band at the lower edge of the sheet. Utilizing the methods of the prior art, these parallel bands upon the sheet of material may be laid closely adjacent each other and sharply demarcated from each other. Combined with the present invention it becomes possible to lay upon a sheet, as shown in Figure 8, a pattern of color areas each sharply demarcated from the color area which is adjacent to it in the direction lengthwise of the sheet 1 as well as in the direction transversely of the length of the sheet.

Utilizing the prior art method of laying parallel bands of granular material upon the sheet, 45 strips of covering material may be made by cutting the sheet transversely of its length, these strips having thereon color areas or sections adjacent each other and sharply demarcated from each other. Utilizing the method of the invention, however, strips of this character may be produced by applying the color areas in adjacent arrangement lengthwise of the sheet 1 and sharply demarcated from each other, the sheet being cut longitudinally thereof in the lines at which 50 the lengthwise bands thereon met. Strips formed in the manner of the invention may be of different lengths or if desired may be of the same length and may be formed by cutting the band transversely thereof at a desired point. Moreover, if desired, these longitudinal cuts and the transverse cuts may be made without regard to the line of separation or demarcation of the color areas to produce either sheets having a portion 55 thereon or elements of any desired dimensions, said sheets and elements having thereon color areas of contrasting appearance each sharply demarcated from its adjacent color area.

Moreover, it will be noted that not only is the width of the several bands upon the sheet 70 1 in Figure 8 different in the direction of the width of the sheet but the dimensions of the color areas in the direction of the length of the sheet 1 are different. By means of the methods of the prior art the longitudinal bands upon the 75

sheet may be made of different transverse width to secure different dimensions of the color areas in the direction transversely of the length of the sheet. By means of the method and apparatus 5 of the invention the dimension of the color areas lengthwise of the sheet may be varied in the manner hereafter to be described. It thus will be apparent that not only the color areas which are contrasting in appearance and sharply de- 10 marked from each other both in the lengthwise and the transverse direction may be produced upon a sheet of material but that the dimensions of these color areas in both the longitudinal and transverse direction may be varied. By means 15 of the present invention these dimensions in the direction lengthwise of the sheet 1 within the limits of the particular apparatus being used may be varied at will.

Figures 1 and 2 show in elemental form the 20 fundamental feature upon which the invention is based. In these figures the sheet of material to be covered with granular material is represented by the numeral 1. In its simplest form, above and separated somewhat from the sheet 1 is a 25 fixed plate 3 of such thickness that a slot 5 may be formed therein with a substantial depth. Above the plate 3 is shown diagrammatically a magazine 7 having formed therein compartments 8, 9 and 10 containing differently colored granular materials. These compartments are separated and formed by the walls or partitions 12, 13, 14 and 15. The thickness of these walls is such in relation to the width of the slot at its upper end that, as shown by Figure 2, a partition 30 14 may completely cover the upper opening 16 of the slot 5 to cut off delivery to the slot 5 of granular material from the compartments 9 and 10 which are separated by the partition 14. When the partition 13 is in register with the slot 5 it also may close the upper opening 16 of the slot and thus cut off delivery of the granular material thereto from compartments 8 and 9. The walls 12 and 15 may also be made to effect 35 such cut-off but, as will be shown hereafter, this relationship of the walls 12 and 15 is not necessary when, as in the simple embodiment being described, the magazine 7 is reciprocated upon the plate 3 so as successively to bring in register with the slot the compartments 8, 9 and 10.

In Figure 1 the slot 5 is shown in the position 50 of full opening produced by movement of the magazine 7 in the direction of the arrow so that partition 13 has been moved out of register with the opening 16 of the slot 5. During this motion of the partition 13 out of register with the slot 5 a certain amount of granular material has flowed into the slot 5 from the compartment 9. This material is deposited directly upon the previously deposited granular material 18 which was 55 received by the slot 5 from the compartment 8. As withdrawal of the granular material 18 from the bottom of the slot 5 proceeds, feeding of the granular material 19 from the compartment 9 continues until, by continued motion of the magazine 7 over the plate 3 in the direction of the arrow, the partition 14 comes into full register with the opening 16 of the slot 5 as shown in Figure 2 and the granular material 19 is cut off. During this movement of the magazine 7, by 60 withdrawal of the previously deposited granular material 18 through the lower opening 20 of the slot 5, the upper surface in the slot 5 of said previously deposited granular material 18 will have moved downward from its position at cut- 65 off by the partition 13 and beyond the position

shown in Figure 1 to the position shown in Figure 2.

Thus there has been deposited in the slot 5 a measured quantity of the granular material 19 received from the compartment 9. This 5 measure is determined by the volume within the slot 5 above the upper surface of the previously deposited granular material 18 at the instant of cut-off by partition 14 of the material 19 being delivered to the slot 5 from the compartment 9. 10 It is a feature of the invention that at this instant of cut-off the previously deposited material 18 has not yet been duly discharged through the lower opening 20 of the slot 5. The depth of the slot provided by the thickness or height of the 15 plate 3 is such that variation in the volume of the material superimposed upon the previously deposited material 18 may be secured without causing said previously material 18 to be fully discharged from the slot 5 before cut-off. 20

The width of the slot, that is, the dimension thereof, in the direction of the movement of the magazine 7, is relatively small with respect to length of the slot in the direction transverse to said motion and parallel to the sheet 1. 25 This width is made small enough to produce the even feed and flat surface of the mass within the slot but is made great enough to permit the masses to move downwardly in the slot without forming a restricting orifice. While 30 the slot, as shown in Figures 1, 2, 5 and 7 is of tapered section, it may be made with parallel walls as shown in Figure 3. The slope of these walls when the slot is of tapered section preferably is not at a marked angle to the vertical 35 and such taper is given merely to provide a suitable dimension of the upper opening 16 of the slot with respect to the width or thickness of the partitions 13 and 14, or their equivalents in the modified forms of the apparatus, and to provide an opening through which the granular material may freely be fed into the slot, in consideration of the restriction of the width of the slot to maintain even feed and a flat surface of the granules as above described. The proper 40 proportioning of these parts may result in a tapered slot or one with parallel sides under different conditions. Moreover, the proportions may be different for different sizes of granular material. 45

It thus becomes possible to cause the granular material to feed through the slot not under the control of gravity alone but, while utilizing gravity to aid the flow, in a suitable relation to the motion of the sheet 1. If the sheet 1 is moved in the direction of the arrow as shown in Figures 1 and 2, the granular material 18 will be withdrawn and will be deposited upon a certain portion of the length of the sheet. If there were no motion to the sheet 1, owing to the relatively 50 narrow dimension of the opening 20 of the slot 5 and in view of the position of the sheet 1 relatively close to the plate 3, there would be no flow of the granular material from the slot to the sheet. As the sheet 1 moves in the direction of the arrow, the granular material is moved from the point immediately below the opening 20 and the granular material 18 above this point may flow down or uniformly settle to replace that removed. Thus a uniform delivery of the material through the opening 20 may be obtained. The amount of materials so removed due to motion of the sheet 1, and the amount replacing the amount so removed, are determined and controlled by the rate of movement of the sheet 1 55 60 65 70 75

and the height of the plate 3 above the sheet 1. These two functions of the device determine the quantity of material laid upon the sheet 1 in a given time or in relation to a given length of the sheet 1.

It will now be clear that as the magazine is moved from the position shown in Figure 2 where a measured amount of the granular material 19 has been delivered into the slot 5, and 5 during the time in which the partition 14 covers the opening 16 of the slot, the sheet continues to move and removes granular material 18 from the slot 5 with the concomitant settling or movement downward of the material 19 in the slot 5. 10 When the partition 14 has moved to the left so as to start opening of the slot below the compartment 10 the granular material from the compartment 10 will start to feed into the slot 5 and to be super-imposed upon the granular 15 material 19 therein. It now will be understood that it is immaterial, for proper action of the apparatus to produce the desired result, that during the time interval in which the slot is closed by the partition 14 no material is being fed thereto. When the slot is fully uncovered the 20 opening 16 is unrestricted and the material 19 may flow freely into the slot 5 to fill it. Thereafter when cutoff is completed the quantity of material 19 which has been fed into the slot 25 will have been determined by the volume of the slot above the previously deposited material and not solely by the timing of opening and of cut off effected by the movement of the partitions 13 and 14 with respect to the upper opening 16 30 of the slot. This feature is an important feature of the invention and is made possible by the design of the slot which maintains a substantially even surface of the granular material throughout the length and width of the slot in the horizontal plane and by the positive determination 35 of the withdrawal of the material from the slot. This withdrawal, as stated above, is not alone under action of gravity but by pre-determined motion of the sheet 1 and the position of the sheet 1 beneath the plate 3 which substantially 40 provides an orifice in the vertical plane having a height equivalent to the distance that the upper surface 22 of the sheet 1 is below the lower surface 23 of the plate 3. 45

It will now be clear that when the entire amount of the granular material 18 has been laid upon the sheet 1 that immediately and without break between the mass of the material 18 and the mass of the material 19, the feed of the 50 granular material 19 will continue. Upon the sheet 1 will be spread a layer of the granular material 18 having a uniform thickness and this layer will be immediately followed by a layer of the granular material 19 of uniform and equal thickness, the areas covered by these two masses of granular material being sharply demarcated from each other because of the sharp demarcation between the masses of the two materials 18 and 19 as they are delivered through and 55 withdrawn from the slot 5 in contiguous and consecutive relation.

In the elemental embodiment of the invention being described in connection with Figures 1 and 2, the magazine 7 may be continued in its motion 60 in the direction of the arrow, until full opening of the slot 5 is effected in register with the compartment 10. After such full opening has been effected and the slot 5 has received from the hopper 10 sufficient material to fill the slot, said 65 material being superimposed upon the material

19 which then will have moved downwardly in the slot, the motion of the magazine 7 may be reversed until again the partition 14 covers the upper opening 16 of the slot to cut off delivery of the granular material from the compartment 10. 5 It will now be understood that successively the compartments 9 and 8 may be brought into register with the slot 5 and the materials contained therein may be successively deposited in the slot. 10 These masses of material, being of contrasting color or character, will be sharply demarcated from the previously deposited masses and, when laid successively upon the sheet in the manner described, they will cover a predetermined area of said sheet and will each be sharply demarcated 15 from the other without space therebetween and without overlapping of one color by those of another color. Thus it will be seen that by a reciprocation of the magazine 7 above the plate 3, below which plate the sheet 1 is moved with a 20 constant speed, there will be caused to be delivered into the slot successive masses of materials in an order predetermined by the arrangement of the different granular materials in the compartments of the magazine. 25

In this elemental embodiment of the invention any reciprocating motion of the magazine 7 which is effective to bring the compartments successively into register with the slot 5 may be used provided this motion is so timed in relation to the withdrawal of the material from the slot that the slot may be filled with material flowing from one compartment and superimpose upon the material previously deposited in the slot before said previously deposited material is completely withdrawn from the slot 5. The dimension of the compartment transversely to the direction of movement of the magazine 7 and parallel to the sheet 1 may, of course, be sufficient properly to fill the slot throughout its extent in said transverse direction. The width of the compartments and the thickness of the partitions and walls 12, 13, 14 and 15 may be such as to provide a substantial volume of the granular material of each color or character in the compartments so that 35 the granular material may readily fill the slot when the compartments are in register therewith. As has been stated above, however, the thickness of the partitions or that portion of them which is in contact with the plate 3 is so related to the 40 width of the slot as properly to effect the cut-off of the granular material when said partition completely covers the slot. The amount of movement which must be given to the magazine 7, it will be understood, depends upon the width of the compartments and upon the thickness of the partitions, and the mechanism must provide for so moving the magazine 7 as to bring the partitions into register with the slot at the proper time so as to effect the cut-off when the previously deposited 45 material, as it is withdrawn by the sheet 1, has moved downwardly in the slot to such a point that the desired metered amount of the material being superimposed thereon has been fed into the slot from the particular compartment. It will 50 be understood, therefore, that it is a feature of the invention so to move the magazine, in consideration of the width of the slot 5 and of the thickness of the partitions 13 and 14 and of the width of the compartments 8, 9 and 10, that cut-off of the several contrasting granular materials 55 will be effected at the proper time with respect to the amount of material of a given color or character already withdrawn and deposited on the sheet 1 as it moves under the slot 5 and there- 60 65 70 75 75

after to uncover the slot 5 and cause the material from the succeeding compartment to flow thereto, cut-off of said succeeding material being effected at the proper time after withdrawal of 5 a defined amount of the previously deposited material of given color. Thus the motion of the magazine 7 must be effected in a predetermined relation to the motion of the sheet 1.

In Figure 3 is diagrammatically shown a device 10 embodying the features which have been described in connection with Figures 1 and 2 but in which for the reciprocating magazine 7 is substituted a rotary cage 25 which may be fitted as a cylinder into a casing 26. In the walls 27 of the cage 25 15 are formed openings 29 spaced circumferentially of the cylinder. Between the openings 29 and extending from a central hub 30 to meet the wall 27 of the cage 25 are partitions 32 dividing the cylinder into compartments 33 for which the 20 openings 29 form outlets. A shaft 34 may be fitted in the hub 30 and be driven by suitable means not shown. As the cage 25 is caused to rotate by rotation of the shaft 34 the openings 29 successively come into register with the upper 25 opening 16 of a slot 5 similar to the slot 5 shown in Figures 1 and 2. It will be apparent, if the compartments 33 are charged with granular color masses of different color, that the delivery of the granules through the openings 29 may take place 30 substantially in the same manner as delivery of the granular material from the compartments 8, 9 and 10 of Figures 1 and 2, and successively different colored granules may be delivered to the slot 5 and in the slot may be superimposed 35 upon each other in the same manner as described in connection with Figures 1 and 2. However, it will also be clear that by means of the device shown in Figure 3 a continuous motion in one direction only of the compartment is effected, 40 and that the sequence of the changes from granular material of one color to that of another color is not limited on account of the reciprocating motion as is the case in Figures 1 and 2 where the sequence necessarily is reversed when, 45 after delivery of granules from the end compartments 8 and 10, there then must follow delivery of the granules from the middle compartment 9 of the apparatus shown in Figures 1 and 2.

By using a magazine having a large number of 50 compartments it is of course possible to effect a practical variation of the successively different colors and in most cases the reciprocating form of the device is preferable. With the device shown in Figure 3, however, the compartments 33 55 may be charged through a delivery hopper 35 as the openings 29 come into register with this hopper at the upper portion of the device. By suitable means there may be delivered to the hopper 35 granules of a given color when the opening 29 60 of a given compartment is about to come into register with the hopper 35. The compartments, therefore, may be charged with color masses arranged in a predetermined order. It will be clear that the order determines the arrangement of the 65 different color masses upon the sheet since the successive compartments 33 come into register with the slot 5 in the order in which they are charged with the different colors.

As has been referred to above in the general 70 description of the invention, instead of reciprocating the magazine 7 of Figures 1 and 2 over the plate 3, equally effective motion of these two parts may be produced, to cause delivery of the granular material into the slot and the cut off 75 of the material therefrom, if the plate 3 is recipro-

cated under the magazine 7, this magazine in such case being fixed relative to the motion of the sheet 1. Thus, if the plate 3 as shown in Figures 1 and 2, is moved in the line of motion of the moving sheet 1 the slot may pass successively beneath the compartments 8, 9 and 10, and receive in like order and in like manner as described above, the granular materials from these compartments. It will be understood, however, when such reciprocating motion is given to the plate 3, 10 the sheet 1 moving with a constant speed with respect to the magazine 7, that the motion of the plate 3 with respect to the sheet 1 and, therefore, of the slot as determining the point of delivery of the granular material, is changed. 15

If the plate 3 is moved in the direction of motion of the sheet 1, the relative speed of these two parts is reduced and when the plate 3 is returned in the opposite direction the relative speed of these parts is increased. It will be seen that 20 the whole movement or displacement of the plate relative to the magazine 7 is the same for the forward and for the reverse motion of the plate. Because of the difference in relative speeds there will be withdrawn from the slot 5 during the 25 time when the plate 3 moves forward in the direction of motion of the sheet less material than when said plate moves in the reverse direction. During these two times, however, or during such parts of these time intervals as is represented by 30 the motion of the slot into and out of register with a compartment of the magazine, there would be delivered into the slot that amount of material which is determined, not merely by the time relation between the plate 3 and the magazine 7 but 35 by the speed of withdrawal of the material as determined by relative motion of the sheet 1 and the plate 3 in view of the spacing of the sheet 1 below the plate 3. The result of this unequal 40 delivery of the material during the forward motion of the plate 3 with respect to the reverse motion thereof is that the material will be laid upon the sheet over a greater length of the sheet 1 during the reverse motion than will be laid upon the sheet during the forward motion of 45 the plate 3. While the extra material required for withdrawal from the slot will readily flow into the slot from the compartment of the magazine in 50 register with which the slot is positioned, in order to produce uniform color areas, or color areas 55 upon the sheet which have a predetermined dimension in the direction of the length of the sheet, it becomes necessary to compensate for the difference in relative motion of the plate 3 with respect to the sheet 1 in the two directions of its 55 movement. The method of and the means for effecting this compensation will be described in connection with a practical embodiment of the invention as shown in Figures 4, 5 and 6.

In Figures 4, 5 and 6 a frame 40 is provided at 60 each side of the apparatus, these frames being suitably connected by bracing members therebetween comprising tie rods 42 and pipe spacers 44 as well as by cross bar 46. The frame 40 may be made of cast iron and may be provided with flanges 65 connected by a central web to provide the desirable stiffness of the frame and also to afford a form of material suitable for finishing as bearing surfaces or surfaces upon which may be attached bearing blocks or other parts. Attached to the frame 40 70 upon the flange 48 thereof is a bearing bracket 50. This bracket may be attached to the flange 48 by bolts 49 passing through the flanges of the two pieces. The upper flange portion 52 of the bracket 50 is formed with a slot 53 as shown in Figure 75

4, this slot being provided with an enlarged portion 54 for receiving the head of a bolt 58, which bolt then may be moved, with the shank thereof in the portion 53 of the slot, lengthwise along the 5 flange 52. Mounted upon the upper flange 52 is a bearing block 56 which, by means of bolts 58, may be fastened upon the bracket 50. As the bolts 58 may be slid lengthwise of the slot 53 with the heads thereof in the portion 54, the bearing 10 block 56 may be moved in the direction parallel to the upper flanges 41 of the frames 40 and 52 of the bracket 50. At the opposite end of the upper flange 41 of the frame 40 may be positioned the bearing block 60. This block may be fastened in 15 a fixed position upon said upper flange 41 by suitable bolts 62. There is provided a bearing block 56 supported upon the upper flange 52 of each bearing bracket 50 attached to each frame 40 of the machine. Also there is a bearing block 20 60 fastened to the upper flange 41 of each frame 40, the respective blocks upon the respective frames being in like position in relation to the frames.

Journalized in the blocks 56 is an apron roll 57 25 which may be formed of steel tubing of suitable diameter and thickness to provide a stiff roll having gudgeons or stub shafts 59 fitted therein and turned upon their ends to fit the bearing surfaces of the bearing blocks 56. Journalized in the bearing blocks 60 is a similar roll 63 which also may be formed of tubing and may have stub shafts fitted thereto for bearing in the bearing blocks 60.

Passing over the rolls 57 and 63 is an apron 65 30 formed as an endless band or belt and of flexible material capable of being driven by friction of the roll 63 when said roll 63 is caused to be turned by means hereafter to be described and also itself to cause the roll 57 to turn on its bearings. The feeder or apron 65 may provide a substantially 35 even surface upon the upper face of the upper stretch thereof in relation to which face the slot carrying structure may be so positioned as to effect feed of the granular material toward and to lay the granular material upon said face of the 40 apron. Said upper stretch of said apron 65 may slide over and be supported against sagging by 45 plate 71 hereafter referred to.

The arrangement of the bearing blocks 56 and 60 and of the rollers 57 and 63 carrying the apron 65 is such that the frames 40 carrying the various 50 parts described, as an assembled device, may be positioned in a roofing machine having rollers 68 and 69 over which a web of roofing felt or other fabric being surfaced may pass, or these rollers 55 may be mounted to run in frame 40 as shown in Figure 5, so that the direction of motion of the band or belt 65 is in a direction parallel to that of the motion of the sheet 1. Thus it will be clear 60 from a consideration of Figures 4, 5 and 6 that, as the sheet 1 is moved in the direction from the roll 68 to the roll 69, granular materials laid upon the band or apron 65 may be caused to be delivered upon the sheet 1 by feeding the upper strand or stretch of the apron 65 in the direction parallel 65 to the motion of the sheet 1, preferably in the same direction, that is, toward the left in Figure 5 so that when the granular materials reach the curve of the roller 63 they may fall upon the sheet 1 and may be laid thereon over a length of 70 the sheet 1 which is determined by the amount of material delivered over the roller 63 for a given length of the sheet 1 passing beneath the roller 63.

It will be apparent that, if upon the feeder or 75 apron 65 has been laid a layer of granular ma-

terial of uniform thickness and of predetermined length in the line of motion of the band, depending upon the speed of delivery of the granular material over the roll 63 as determined by the speed of the band 65 relative to the speed of the sheet 1, said mass of material will be delivered upon a given length of the sheet 1. Moreover, if, in the manner described above in the simple embodiment of the invention, there has been laid upon the feeder or apron 65 contiguous color masses upon successive areas of the apron 65 and sharply demarcated from each other, these successive color masses will be laid upon the sheet 1 in the same order as they are laid upon the apron 65 and with like sharpness of demarcation one from the other. A feature of the invention which insures this sharp demarcation of one color mass from the contiguous color mass is that the granules fall through only a relatively short distance from the roll 63 to the sheet 1 and thereby differences in air resistance or of rebound from the apron, or of other factors which may be due to differences in size of the granules, are minimized and therefore produce no great variations or differences in the speed with which the different granules fall to the sheet with the result that the granules which leave the apron together fall substantially together and lie upon the sheet in like proximity.

Bearing upon the upper flange 41 of the frame 30 40 as may be seen in Figure 6 is fastened by suitable bolts 70 a side bracket 72 from which by means of bolts 74 passing through lugs 75 of the side brackets 72 are suspended cross bars 76, one at each end of the bracket 72. The cross bars 35 76 extend transversely of the motion of the sheet 1 and of the apron 65 and carry a plate 77 which serves to support the upper stretch of the apron 65 and maintain it in a horizontal plane throughout the extent of its travel beneath the field of operation of the slot mechanism. The bolts 74 are threaded at their lower ends into the cross bar 76 so that by turning the bolt while its head bears on the lug 75 the ends of the bars 76 may be lowered or raised and thus each corner of the plate 45 77 may be lowered or raised in order to bring the plate into a level position and in a horizontal plane so as to provide a uniform surface upon which the apron 65 may bear. As the apron 65 may have a uniform thickness the upper surface 50 of the apron also will thus provide a uniform level surface in the horizontal plane. By means of the bolts 74 the plate 77 may be positioned at a greater or less distance below the lower opening of the slot structure in order to vary the 55 height of the vertical orifice and thereby the thickness of the granular layer. This setting, for example, may be such that the upper face of the upper stretch of the apron 65 may be $\frac{1}{16}$ " to $\frac{1}{8}$ " below the slot opening. The invention, however, 60 is not limited to this specific range of setting and settings of greater or less amount may be used.

Fastened in the side bracket 72 by means of nuts 89 are studs 82 having heads 83 and providing bearings for rolls 84 turning thereon. A 65 stud 82 and a roll 84 is provided, as shown in Figures 5 and 6, adjacent each end of the side bracket 72 and, as may be seen from Figure 4, a set of studs is provided for each side bracket 72. These studs and rolls provide bearings upon which 70 may roll, in a direction tangent to the circumferences of the rolls 84 and in a horizontal plane parallel to the plane of the apron 65, the carriage 85 in which is formed the metering slot.

This carriage 85 comprises a frame 86 having 75

a plate 88 bearing upon the top edge thereof. This plate provides a smooth and even surface upon its upper face. Upon the underside of the plate 88 and to the portions thereof which extend over frame 86 are fastened by suitable means such as welding bearing strips 89 which have their lower faces formed parallel to the plane of the upper face of the plate 88. The strips 89 are positioned adjacent the lateral edges of the plate 10 88 and so as to bear in rolling contact upon the rolls 84. As the plate 88 may be fastened by suitable means such as welding to the frame 86 this frame thus may be caused to move in a horizontal plane and parallel to the plane of the upper face of the apron 65.

Adjacent the central portion of the carriage 85 and spanning from one side to the other of the frame 85 is a cross member 90 in which is formed an opening 91 extending from one of the lateral members of the frame 86 to the other. The opening 91 may be of such width in the direction of the motion of the frame 86, that is, in the direction of the motion of the apron 65, as to provide room for liner plates 92 to form therebetween a slot 93 in the carriage 85. These liner plates may be of suitable wear resisting material and may be made removable from the cross member 90 so that after wear upon the inner faces of the liner plates 92 has occurred to an undesirable

30 extent they may be removed and new liner plates inserted. The space between the inner faces of the liner plates 92 forms the slot 93 with its length extending transversely of the motion of the frame 86 and, therefore, of the motion of the apron 65, 35 and for the full extent of the transverse dimension of said apron 65. The opening 91 in the transverse member 90 is so formed and the thickness of the plates 92 is such that the slot 93 is formed with its side faces tapering with the wider 40 opening at the top and the narrower opening at the bottom in order to produce the friction action and the effects which have been described above. The slot opening 93 is continued up through the plate 88 as shown in Figure 5. In a practical embodiment the width of the slot 93 at its upper 45 opening may be about $\frac{3}{8}$ " while the width at its lower opening may be about $\frac{1}{4}$ ". These dimensions are merely typical and may be varied to suit different conditions, such as different size 50 or character of the granular material or differences in the construction of the apparatus, while securing the even surface of the granular material as described.

It will now be clear that the slot 93 may be 55 moved in the plane parallel to the plane of the apron 65 and if the lower edge 87 of the transverse member 90 is at a small distance above the upper face of the apron 65 the granular material moving down through the slot 93 may be deposited upon the upper face of the apron 65 and 60 may lie thereon as a layer having a thickness determined by the distance between the lower edge 87 of the slot structure and the upper face of the apron 65.

Bearing upon the upper face of the plate 88 and held against motion in the horizontal plane by upright studs 95 fastened at their lower ends in the side brackets 72 is a box or magazine 98. The box 98 is constructed with a lower plate 100 70 forming the bottom thereof and suitably fastened to the angle frame 101 as shown in Figures 5 and 6. The angles 101 serve to support the side plates 103 of the box 98, these side plates being fastened at their upper edges to angle frame 104 to complete a rigid magazine frame.

In the plate 100 are formed openings or slots 106 which extend across the plate in a direction parallel to the length of the slot 93 for the full length of said slot 93. These openings 106 are of such width in the direction of motion of the carriage 85, that is, the direction of motion of the apron 65, that between said openings 106 may be left portions 108 of the material of the plate 100. The width or thickness of these portions 108 in said direction of the motion of the carriage 85 is such as fully to cover the upper opening of the slot 93 when said portions 108 are in register with the slot. The width of the openings 106 also is such that partitions 109 extending upward from each of the portions 108 of the plate 100 may be so positioned as to form compartments or pockets of such width and extending fully over the transverse dimension of the plate 100, as to provide space for a substantial amount of the granular materials, such as 15 granular slate, placed therein. The width of the openings 106, therefore, is made as great as is possible and greater than the width of the upper opening of the slot 93 without interfering with the provision of sufficient thickness or width of 20 the portions 108 to secure the necessary overlap of said portions upon the upper openings of the slot 93 in order to cut off the flow of granular material into the slot. 25

It will now be apparent that when a compartment formed between the partitions 109 or between a partition 109 and the wall 103 of the box 98 is above the slot 93, the material from the compartment may run into the slot under the action of gravity until the material reaches the upper face of the apron 65 and builds up thereon to the lower edge of the slot 93. Thereafter, the material will fill up the slot 93 until the mass of material is continuous from the compartment to the slot. If, now, in the manner described above the apron is moved relative to the slot the granular material will be withdrawn from the lower end of the slot and the granular material will thereafter again run from the compartment into the slot at a rate determined by the speed of the apron 65 with respect to the slot 93. 45

As, in the embodiment being described, the carriage 85 is arranged to move in a horizontal plane parallel to the face of the apron 65 and, by means hereafter to be described, may be reciprocated in this plane, it will be apparent that the slot 93 may be moved successively under the different openings 106 which are in the plate 100 and which provide outlets for the material in the different compartments. The interval of time in which the slot 93 carried by the frame 86 55 may be moved from the position of cut-off of material from one compartment to that of the cut-off of the material from the succeeding compartment substantially may equal that required to withdraw from the slot a given amount of the material in the slot, which amount, for the purposes of the invention, will be a color mass. While the rate of flow under the action of gravity of the material from the compartments into the slot 60 is not and need not be definitely limited to the rate of withdrawal of the material from the lower opening of the slot it will be apparent that when the slot 93 starts to open, by moving from under one of the portions 108, material from the compartment into register with which the slot is 65 moving may start to flow into the slot. In the slot there will be a certain amount of space which will be formed by withdrawal of the material from the slot during said interval from the 70 75

time of cut-off of the flow from the preceding compartment until the opening of the slot under the succeeding compartment. Thereafter the material from the compartment will follow the withdrawal of the material from the slot until again flow from the compartment is cut off by movement of the slot completely under a portion 108 of the plate 100.

It will now also be apparent that between the 10 upper surface of that color mass which has been previously cut off from the compartment from which it flowed, and which has moved downward in the slot by withdrawal from the bottom thereof, and the upper opening of the slot, that is, 15 the under face of the plate 100, there will be a metered amount of granular material which for the reasons which have been stated above, is sharply demarcated as a color mass from said preceding color mass in the slot. As this color mass 20 within the slot 93 is withdrawn at a rate predetermined by the rate of motion of the apron 65 with respect to the slot, and in consideration of the height of the lower edge 87 of the slot above the upper face of the apron 65, said metered 25 amount of granular material as a color mass will be laid upon a definite length of the feeder 65 and said definite quantity of granular material as a color mass upon the apron 65 will be delivered upon a definite length of the sheet 1 as it passes beneath the delivery end of the apron 65.

As may be seen from Figures 4, 5 and 6, surrounding the upright studs 95 are springs 96 upon the horizontal flanges of the angles 101. The compression of the springs 96 may be adjusted by means of the nuts 97. As the lower face of the plate 100 is a plane surface and therefore may fit against the plane surface of the upper face of the plate 88 of the carriage 85, said carriage may be reciprocated with continuous 40 contact of these faces, the pressure of the plate 100 upon the plate 88 being transmitted to the rolls 84. Thus is secured sharp cut-off and opening of the slot 93 from and to the successive compartments containing the granular material 45 of different colors. The pressure applied by means of the nuts 97 is such as to secure close contact of the faces of the plates 100 and 88 but is insufficient to cause an amount of friction between these faces such as will interfere with the reciprocation of the carriage 85 as described. 50

To the plate 88 are fastened extension brackets 115 at either side thereof which brackets are formed at their outer ends with threaded portions upon which are fitted nuts 116. Engaging the 55 brackets 115 and held thereon by the nuts 116 in pivotal relation thereto are links 118 which are formed at the ends thereof opposite to that of engagement with the extensions 115 with a forked portion 119, as shown in Figures 4 and 6. 60

The link 118 is connected to the rocker arm 122 by means of a pin 120 passing through the forks 119. The lower end of the rocker lever 122 is pivoted upon a shaft 124 having a bearing 126 in the frame 40 as shown in Figures 4, 5 and 6. 65 The shaft 124 extends through the frames 40 on each side of the machine. As the rocker arms at their lower ends are fastened upon the shaft 124, there also being connecting links 118 on each side of the machine connecting to these rocker arms, and as the parts may be arranged at either side of the machine in like relation to the plate 88 and its extensions 115, when motion is imparted to the rocker arms they move in unison and apply force evenly to effect movement of the carriage 85 in the horizontal plane. 70

In order to produce the rocking motion of the arms 122, attached to each of said arms by means of clamps 127 having set screws 128 is a bracket 129. The clamps 127 are fastened to the bracket 129 and the set screws 128 are arranged to engage 5 the edges of the arm 122 so that the position of the bracket 129 may be adjusted along the arm 122. At the end of the bracket 122 is fastened a stud 130 by means of a nut 131. This stud 130 carries a cam ball or follower 132 arranged to 10 engage the cam groove formed in a cam disc 134. The cam groove is formed by the walls 136 and 138 having the adjacent faces thereof parallel to each other and parallel to the line of 15 formation of the cam, upon which line of formation the center of the cam ball moves with respect to the cam. Cam 134 is fastened upon a shaft 140, there being a cam at each end of the shaft as shown in Figure 4, each cam being arranged in like angular relation about the axis of 20 the shaft 140 so that when the shaft is turned by means to be described, like points on the cam move in like angular relation to a plane, for example, the vertical plane, passing through the 25 axis of the shaft 140.

It will be apparent from a consideration of the cam outline in Figure 6 that as the shaft 140 is rotated with the cams fastened thereto, the cam ball 132 on each side will be moved with a reciprocating motion in a direction generally from 30 left to right and back again. The levers 122 will be reciprocated with angular displacement about the shaft 124 with the result that the carriage 85 and the plate 88 to which the links 118 connect also will be reciprocated in the horizontal plane. 35 The cam will determine the amount of reciprocating movement of the cam ball 132, and therefore, of the carriage 85 carrying the slot 93 with respect to the openings in the plate 100 of the box 98. The slot 93, therefore, will be caused 40 to move successively under each of the compartments of the box 98 to receive therefrom successively the different color masses, the quantity of these masses so received being metered in the manner described above. 45

When the carriage 85 is moved in the direction of motion of the apron 65 the relative movement of the slot 93 with respect to the apron 65 will be less, in the time interval in which the slot passes from one compartment opening to the other, than the relative movement of the slot 93 with respect to the apron 65 during a corresponding interval in the reverse motion of the carriage 85. Compensation for this difference in the relative movement is accomplished by means 55 of the forms of the cam in its two portions which effect motion in one direction and in the other. These portions are so formed that during the stroke of the carriage 85 in the direction in which the apron 65 is moving the rate of the forward movement of the carriage is made less than the rate of movement in the reverse direction. The cam is so formed that, during the forward movement, namely, movement in the same direction as the movement of the upper strand or portion of the apron 65, the full throw of the cam producing the full stroke of the frame 86 is made in a greater angular motion of the cam and therefore in a greater time than the throw which produces motion of the carriage 85 in the reverse direction. 60

In Figure 6 the radius from the center of the shaft 140 to the point A in the cam groove determines, when the cam ball 132 is at point A, the position of the carriage 85 at that end of the 65 70

stroke from which it will move forward in the direction of motion of the apron 65. This end of the stroke is that at the right hand of Figure 5 or the left hand of Figure 6 and opposite to that at which in Figure 5 the slot is positioned. As the cam turns upon the axis of the shaft 140 the cam ball 132 will be moved in the groove to the position shown at B in Figure 6, which corresponds with the position of the slot as shown in Figure 5, namely, at the left of said Figure 5 and at that end of the stroke of the carriage 85 which is at the extreme of the motion in the direction of movement of the apron 65.

15 It will be apparent from Figure 6 that as the cam 134 rotates in the direction of the arrow the cam ball 132 will move along the cam groove from B to A, that is, along the shorter portion of the groove and correspondingly through a less angular displacement of the cam than that which will effect movement of the ball 132 along the groove from A to B. As the cam ball 132 is moved from its position as shown in Figure 6 toward the left of the figure the carriage 85 is moved toward the left in said figure or toward the right in Figure 5. This movement is in a direction which is the reverse of that of the motion of the apron 65 as it passes over the plate 71. Because of the less angular displacement of the cam 134 the time during which this reverse movement of the carriage 85 is effected is less than the time of the movement of the carriage 85 in the forward direction, that is, in the direction of motion of the apron 65. The speed of 35 the slot 93 over the plate 71, therefore, in the reverse direction is greater than its speed in the forward direction. The forward movement produced by the longer portion of the cam from A to B, being effected in a greater interval of time than the interval for the reverse stroke and the 40 length of the two strokes being equal, a greater length of the apron 65 may pass over the plate 71 during said forward movement than during said reverse movement of the carriage 85.

45 In consideration, however, of the fact that during the forward movement of the carriage 85 said carriage is moving in the same direction as the apron 65 and if, in said forward movement, the lineal speed of the carriage 85 with respect to the plate 71 is less than that of the apron 65 with respect to the plate 71, a movement of the carriage 85 with respect to the apron 65 is produced which, during a given interval of time, is less than if said movement of the carriage 85 were in the reverse direction at the same speed 55 relative to the plate 71.

As, however, the forward movement of the carriage 85 is produced in a longer time by the greater angular displacement of the cam 134, a length 60 of the apron 65 may be caused to pass under the slot 93 of the carriage 85 sufficient to cause withdrawal from the slot 93 of the desired amount of the granular material to lay upon the desired length of the apron. During the reverse stroke 65 of the carriage 85 the relative movement in a given interval of time of the carriage and its slot 93 with respect to the apron 65 is greater and, therefore, the desired length of travel of the apron 65 under the slot 93 may be secured during the shorter interval of time corresponding to the 70 less angular displacement of the cam 134 which effects movement of the cam ball from B to A. By suitably forming the cam, that is, by suitably selecting the relation of the angular displacements thereof which are effective to produce the

two strokes of the carriage 85, the relation of the lengths of the color masses laid upon the apron 65 may be determined. Thus it becomes possible to equalize the two lengths of the surface of the apron 65 upon which color masses are laid during the two strokes by designing the cam for the proper intervals, that is, the correct angular relations, for the two portions of its outline.

10 Since the equalization of the lengths of the apron 65 upon which the total amount of material is laid during the two strokes may be effected by the form of the cam, it is likewise possible, by suitably determining the intermediate points of the cam outline, to bring about the registration of the slot with the successive openings in the plate 100, and consequently the successive charging of the slot 93 with the different color masses contained in the different adjacently arranged compartments of the magazine 98, in such 15 a way as to equalize or predetermine in any desired manner the lengths upon the apron of the successive color areas.

20 As an illustration of the function of the cam 134, if color areas of equal length in the direction 25 of movement of the sheet 1 are to be formed thereon, the cam may be of such outline that the metering slot 93 may move from, say, the cut-off position with respect to one compartment of the magazine 98 to the cut-off position with respect 30 to the next compartment while the sheet 1 is traveling through a distance, measured with respect to the metering slot, which itself is moving, equal to the desired length of the color areas. The angular movement of the cam 134 is a measure 35 of the lineal movement of the sheet 1 and of the apron 65 with respect to the machine and the cam outline determines the movement of the carriage 85 with respect to the apron 65 so that the slot 93 in the carriage 85 is moved equal distances with respect to the apron 65, that is, with respect to the sheet 1, in the time of movement of the slot 93 between said successive cut-off positions.

40 While a smooth cam has been drawn between 45 points A and B in the illustrated embodiment, it will be understood that a cam of stepped form with steps corresponding to the registrations with the different and successive compartment openings may be utilized. Such a cam would effect 50 a quick motion of the slot from its registration with one compartment opening to the next rather than a continuous movement from one registration to the other. In the practical embodiment of the invention being described and illustrated in the drawings it is preferable and more convenient to utilize a smooth cam so that the mechanical action of the parts may be simplified and so that they may be produced at less expense. 55

60 As in the smooth cam, the angular movement of the cam between steps determines the interval 65 of time between movement of the carriage from its position in registration with one compartment of the magazine to the position in registration with the succeeding compartment. This angular movement may be equal for successive movements of the carriage or may be unequal depending upon whether it is desired to lay upon the sheet color masses in equal or unequal lengths throughout the stroke of the carriage. The cam, therefore, in its outline, whether as a smooth outline or in the step form, determines within 70 the stroke the relative lengths of the color areas 75

upon the apron 65 and, therefore, upon the sheet 1.

Since the cam outline determines the total throw of the carriage 85 and also the relative throw effected by the cam 134 in the successive portions of its outline to produce motion of the carriage 85 between the successive compartments of the magazine 98, a cam of given outline may be used to produce a succession or set of color areas upon the sheet, which color areas may be in the same relative proportions to each other as to length as a succession or set of color areas upon the sheet produced by the same cam but over a greater or a less total length of the sheet.

15 1. The compensation or equalization effected by the difference in the form of the cam for the two strokes thereof may be secured equally well under the two conditions just mentioned. The variation of the total length of the sheet over which the succession of color areas is laid in the two cases may be effected by means about to be described.

In order to drive the cam 134 there may be fastened upon the shaft 140 a gear 142 meshing with an idler gear 144 turning upon a stud 146 movable in a slot 147 in the frame 40. By suitable fastening means the stud 146 may be held in the slot 147 but so that when desired it may be moved along the slot 147, which is formed as an arc of a circle having its center upon a shaft 148, which shaft receives power from the roofing machine by any suitable driving means. Fastened upon the shaft 148 is a gear 149 meshing with the gear 144 so as to drive the gear 144 as the shaft 148 is turned. As the stud 146 swings about the center of the shaft 148 the gear 144 may be swung into or out of mesh with the gear 142. Thus the gear 142 may be driven upon turning of the shaft 148 and may cause the shaft 140 and the cams carried thereby to rotate. Moreover, the rate of rotation of the cam will be in a definite relation to the speed of the sheet 1 which, being driven from the roofing machine, moves in a constant relation to the rotation of the shaft 148. It thus will be clear that the lineal speed of and the rate of reciprocation of the carriage 85 may be in a definite relation to the speed of the sheet 1 as said sheet moves through the apparatus of the invention.

50 With a given speed of the sheet 1 and a given rate of reciprocation of the carriage 85 and with a constant speed of the apron 65, a certain quantity of each color mass will be withdrawn from the successive compartments and will be laid, first upon a given length of the apron 65, and then upon a given length of the sheet 1. Moreover, the cycle of the color masses will be repeated in a given length of travel of the sheet 1. If, now, by fastening a gear 142 of different diameter or number of teeth upon the shaft 140, or substituting for gears 144 and 149 gears having a different ratio, the stud 146 being moved so as to cause the idler gear 144 to engage the gear 142 for the new relationship, the rate of reciprocation of the carriage 85 is changed, for example, is increased, then, with a constant speed for the apron 65 a less amount of granular material will be withdrawn from each compartment in a given interval of time, that is, the interval between registration of the slot with the successive compartment openings because a shorter travel of the apron 65 under the slot 93 will occur in said time interval. During this interval the speed of the sheet 1 is constant and therefore the length of the sheet to which this granular material, that

is, a color mass, will be applied will be less. Correspondingly a decrease in the speed of reciprocation of the carriage 85 will increase the length of the sheet covered. Thus it will be seen that variation in the length of sheet covered by a color mass may be made by changing the ratio of the gears 149 and 142, or otherwise changing the speed of shaft 140 in relation to shaft 148; also the length of the sheet covered by the individual color mass of the sequence of these masses may be changed in this way. Other means which are capable of effecting a change in the rate of the driving of the cam and, as a result, change in the reciprocation of the carriage, may be utilized within the scope of the invention in order to change the length of the color areas.

When with a given cam outline change is made in the ratio of the rotation of the cam 134, that is, of the reciprocation of the carriage 85 to the parts of the mechanism producing motion of the apron 65 and of the sheet 1, the compensation above described, which is produced by the two different angular movements of the cam for the forward and reverse strokes of the carriage is modified and complete compensation for the increased or decreased length of the color area is not secured. This condition will become evident when it is considered that the difference in relative movement of the slot 93 with respect to the apron 65 in one direction is added to the length which the apron travels with respect to the plate 71 and in the opposite direction is subtracted therefrom. When this difference is added to and subtracted from a greater or a lesser length of the color area being produced, the percentage of compensation in the two directions is not equalized.

For example, if the distance which the slot 93 must move from the point of cut-off from one compartment of the magazine 98 to the point of cut-off of the adjacent compartment is $1\frac{1}{2}$ ", during which interval of movement the color mass from said adjacent compartment is delivered into the slot, then when said movement of the slot is in the forward direction, that is, in the same direction as the movement of the apron 65, for a given movement of the apron, say 9" with respect to the plate 71, the movement of the slot with respect to the apron will be $7\frac{1}{2}$ ". When the movement of the slot 93 is in reverse direction with respect to the plate 71 its movement with respect to the apron 65 will be $10\frac{1}{2}$ ". As has been described above, the form of the cam 134 may be made such as to compensate for this difference in order that the movement of the slot 93 with respect to the apron 65 shall be equalized for the two strokes or made in any desired relation. When, however, by reducing the speed of reciprocation of the carriage 85 with respect to the apron 65, as has been described above, the granular material is laid upon a greater length of the apron 65, for example, upon a nominal length of 18", the movement of the slot 93 from compartment to compartment remaining the same, namely, $1\frac{1}{2}$ ", then the movement of the slot relative to the apron in the two directions becomes respectively $16\frac{1}{2}$ " and $19\frac{1}{2}$ ". It will be understood from these typical dimensions, the ratio of $10\frac{1}{2}$ to $7\frac{1}{2}$ being different from the ratio of $19\frac{1}{2}$ to $16\frac{1}{2}$, that the cam which is formed for a ratio of $10\frac{1}{2}$ to $7\frac{1}{2}$, for example, does not exactly fit the condition where the desired ratio is $19\frac{1}{2}$ to $16\frac{1}{2}$. While in certain cases a different cam may be used when color areas of different length are to be formed on the sheet, in many

cases a simpler practical method of producing the change in length of color area without the necessity of utilizing a different cam for every modification of the color area may be adopted. 5
This method will be described hereafter.

In the description of the invention thus far given it has been assumed that the speed of the apron 65 is fixed and therefore in a fixed relation to the speed of the sheet 1. There is thus laid 10 upon the sheet 1 a layer of the granular material of definite thickness because, regardless of the succession of the color masses, the thickness of the layer of granular material upon the apron 65 is determined by the action of the slot structure 15 as described above. Substantially, therefore, there is produced a constant feed of the material at a given point, that is, at the circumference of the surface of the apron as it passes over the roll 63 and a uniform showering and laying 20 of the granules upon the sheet 1.

It will be understood that if the speed of delivery toward the sheet 1 of the granular material of a given thickness upon the apron 65 is reduced, a greater length of the sheet 1 will pass 25 under the point of delivery and, therefore, the granular material will be spread out over a greater length and will be of less thickness upon the sheet 1 than if the speed of the apron 65 were increased with respect to that of the sheet 1. In 30 order to secure the spread of the granules over the desired length of the sheet and with the desired thickness of the granular layer and to effect variations of these actions the invention contemplates the use of a driving mechanism 35 interposed between the shaft 148 and the roll 63 which is of such type that the speed of the roll 63 and, therefore, of the apron 65 driven thereby may be changed with respect to the speed of the shaft 148. The particular type of speed changing device which is utilized forms no part of the invention and any convenient means for effecting variation of the ratio of the revolutions of the roll 63 with respect to the revolutions of the shaft 148 may be used within the scope of the 40 invention.

In the embodiment illustrated in the drawings is shown at 155 the casing of a Reeves drive mounted upon supporting members 156 framed between frames 40 of the machine. This device 45 is of well known construction and is provided with a shaft 157 extending through the casing 155 and having fastened thereto externally of the casing a chain gear 158. The chain gear 158 is driven by the chain 159 from a chain gear 160 fastened upon the shaft 148. The Reeves drive 50 also has a shaft 165 extending through the casing 155 on the opposite side thereof from the gear 158. The shaft 165 has fastened thereto a chain gear 167 driving by means of chain 168 a sprocket 169 fastened upon the roller 63. The 55 construction of the Reeves drive within the casing is such that at will an increase or decrease of the rotation of the shaft 165 with respect to the rotation of the shaft 157 may be produced. Such changes of rotation or of speed of the two 60 shafts 157 and 165 effect proportionate changes in the rotation or speed of the roller 63 with respect to the shaft 148. In place of the Reeves drive other well known variable speed devices 65 may be substituted in order to obtain different speeds of the roll 63 while the speed of the sheet 1 is maintained constant.

If the speed of the apron 65 is increased by 70 increasing the speed of the roll 63 by suitably

operating the variable speed device, then a greater amount of material will be delivered toward the sheet 1 for a given length of sheet 1 passing under the roll 63 and a thicker layer of the material upon the sheet 1 will be secured. 5 Such an increase in the speed of the apron 65, however, if produced without change in the rate of reciprocation of the carriage 85 and of the slot 93, will cause to be withdrawn from the slot 93 and to be laid upon the apron a greater amount 10 of the granular material of each color mass. Although this additional material will be laid upon a greater length of the apron 65 but with the same thickness as before increasing the apron speed, it will be laid upon the same length of 15 the sheet 1 in a thicker layer than before the increase of the speed of the apron 65. Thus variation of the speed of the apron 65 with respect to the sheet 1, while maintaining a given relation of the speed of reciprocation of the carriage 85 20 with respect to the speed of the sheet 1, provides control of the thickness of the granular layer laid upon the sheet 1 without variation of the length of the color areas or their succession as laid upon the sheet 1. 25

From the above description it will be clear that for the purpose of laying color areas which are to have their dimensions in the direction of the length of the sheet in given proportionate relations to each other, for example, if these lengths 30 of the color areas are to be equal, a cam of suitable outline may be utilized and that increase or decrease of the lengths of these color areas while maintaining the proportionate relation thereof, may be secured by changing the driving 35 relation between the cam and the sheet, the driving relation between the sheet and the apron being held the same. In the particular embodiment described, this change may be made by changing the ratio of the gears driving between 40 the shaft 148 and the cam shaft 140. Moreover, without modifying the lengths of the color areas as laid upon the sheet the quantity of material delivered upon a given color area may be varied 45 by varying the speed of the apron 65 by means of a variable speed device such as the Reeves in 50 relation to the speed of the sheet. If, however, for the purpose of changing the length of the color area the driving relation between the cam 134 and the sheet 1 is changed, as by changing 55 the gears 142 and 144 as has been described above, and if at the same time the driving relation between the cam 134 and the apron 65 is changed by adjusting the variable speed device, it 60 has been described above, which is caused by using a cam of such outline as will produce the compensation for one length of color area but not for a different length of color area secured by changing the ratio of the gears 142 and 144 65 alone.

If, as suggested in the last paragraph, change 65 in the driving relation between the shaft 148, which is driven in a constant relation to the means for producing movement of the sheet 1 and the shaft 140 on which the cam is mounted is effected by changing gears 142 and 144 and if at the same time by means of the variable speed device the relation of the speed of the apron 65 70 to the revolutions of the shaft 148 is changed, it will be apparent that the relation of the movement of the apron 65 to the movement of the cam may be restored to that which existed before changing the relation of the gears 142 and 144. 75

Substantially this produces a change in the movement of all the parts of the mechanism of the invention with respect to the parts of the machine which produce the movement of the sheet 1. In other words, change in the movement of the sheet 1 relative to the movement of the apron 65 and relative to the movement of the slot 93 may be secured by effecting a proportionate increase or decrease in the movements of both the apron 65 and of the slot 93. It, therefore, will be understood, if instead of changing the speeds or movements of the parts of the mechanism of the invention, by suitable means in the roofing machine, the speed of the sheet 1 is increased or decreased, that the desired effect will be produced and the granular material may be laid upon a greater or lesser length of the sheet 1.

While in this way the change of the color areas upon the sheet 1 may be effected, by this change alone of the relative speed of the sheet 1 with respect to the mechanism of the invention variation will be introduced in the thickness of the layer of the granular material which is laid upon the sheet. This will be understood since the apron 65 will deliver a constant amount of the granular material to the sheet, which amount will be laid over a greater or less length of the sheet 1 in accordance with an increase or a decrease in the speed of the sheet 1. In order to restore the desired thickness of the granular material upon the sheet, however, the thickness of the layer of the granular material laid upon the apron 65 as it is withdrawn from the slot 93 may be increased by adjusting the position of the plate 77 so that the apron 65 will be at a greater or less distance from the lower edge 87 of the slot structure 90. This adjustment may be effected in the manner described above by means of the screws 74 which are threaded in the crossbars 76, the plate 77 being adjusted to a level or flat position parallel to the plane of motion of the carriage 85. If by increasing the speed of the sheet 1 with respect to the mechanisms of the invention the granular material is laid in a thinner layer upon a greater length of the sheet 1, the plate 77 may be set at a greater distance from the lower edge 87 of the slot structure 90 in order that a heavier layer of the granular material may be carried by the apron 65 and delivered to the sheet 1, the layer upon the sheet 1, therefore, being correspondingly thicker. Similarly, with a reduction of the speed of the sheet 1 with respect to the mechanism of the invention in order to produce a shorter color area, the plate 77 may be set closer to the lower edge 87 of the slot structure 90. When this method of securing change in the length of the color area is used no adjustments of the parts of the mechanism of the invention or change in the ratio of the reciprocation of the carriage to the movement of the apron need be made and a cam of given design suitable for compensation with a given ratio of the movement of the carriage with respect to the apron may be used for all lengths of color area upon the sheet 1.

With a given setting of the plate 77 producing a given thickness of the granular material upon the apron 65, by an increase of the speed of the apron 65 alone more granular material will be delivered to the sheet 1, as has been described above, to produce a thicker layer of the granular material upon the sheet 1. A reduction of the apron speed correspondingly will produce a reduction of the thickness of the granular material upon the sheet 1. By such a change in the speed

of the apron 65, however, there is introduced a discrepancy in the length of the color areas for the two strokes when a cam of given design is utilized. This discrepancy is produced for the same reasons which have been set forth above in connection with a modification of the speed of reciprocation of the carriage by a change in the ratio of the gears 142 and 144. It will be understood that a change in the apron speed, which may be effected, for example, by the variable speed device, substantially is a counterpart of a change in the rate of reciprocation of the carriage 85, since by either change the relative movement of the apron 65 with respect to the movement of the slot 93 is changed.

While the invention has been described in connection with an illustration of its elemental form and in one practical embodiment thereof, many different variations may be made within the scope of the invention in order to carry out the process of the invention and to produce covering elements of the type described. For example, as shown in Figure 7 a feed roll 170 in the form of a cylinder rotating continuously in one direction upon its axis may be used. The structure 172 carrying the slot 173 formed by walls 175 may be arranged also to rotate upon the same axis of the roll 170. The granular material may be withdrawn from the slot by relative movement of the circumference of the roll 170 with respect to the outlet 176 thereof and may be delivered upon the sheet 1 in the same manner as its delivery is effected by the apron 65 passing under the slot 93 and then over the roll 63 as shown in Figure 5. The magazine 178 may be provided with partitions 179 and with outlets 180 similar to those of the construction previously described. The lower wall of the magazine 178 in which the outlets 180 are formed is of cylindrical form conforming to the outer cylindrical surface of the slot carrying structure 172. It will be understood that a reciprocation of the slot carrying structure 172, effected by suitable means, will successively cause the upper opening 177 of the slot to pass into register with the openings 180 and the action which has been described, particularly in connection with the slot 93 shown in Figure 5, will be produced in the same manner as this action is effected by means of the apron 65 and the reciprocating carriage.

In the embodiments of the invention which have been described gravity is utilized to move the granular material from the compartments into and through the slot to the apron. The invention, however, includes within its scope any means or mechanisms which are effective to produce movement of the granules through these passages in the manner and under the control described. Modifications of the various parts of the apparatus and the arrangement thereof to suit different conditions will be apparent to those skilled in the art while maintaining the relations of the parts and their functions which are effective to carry out the process and to produce the covering materials which are the subject of the invention. The invention may be applicable to feeding and control of flowable and miscible materials other than granular materials in connection with which the invention has been described, which other materials are of such character that in the manner described an even surface of contact may be produced between the consecutive masses thereof.

Having thus described my invention I now claim:

1. Apparatus for applying granular material to sheet material which comprises means for continuously feeding granular material toward the sheet, means confining said granular material as it is fed to the sheet, means determining with said confining means a volume through which the granular material is fed to the sheet, said volume being not less than that of a predetermined amount of granular material of given character, means for delivering a mass of granular material of said given character to said volume so as to be fed therethrough, and means for delivering immediately contiguous to but separate from and substantially unmixed with said mass of granular material of given character in said volume a mass of granular material of contrasting character in said predetermined amount, said means determining the volume being so formed and arranged that the surface of the mass of granular material of given character contiguous to which said mass of contrasting character is fed is maintained during said feeding and said masses of granular material are separate and demarcated from each other at said surface. 5
2. Apparatus for applying granular material to sheet material which comprises means for moving said sheet in the direction of one of its surface dimensions, a structure providing a slot between surfaces generally like-extending in the direction transversely of the surface of the sheet and transversely of the movement of the sheet to provide in the slot a volume having an extent transversely of the surface of the sheet, said structure being so mounted with respect to the sheet as to provide a space between the surface of the sheet and the part of the structure forming the portion of the slot which is adjacent the sheet, said spacing of the slot structure in relation to the sheet determining with the movement of the sheet the amount of granular material withdrawn from the slot, and means for delivering to the slot granular material to replace that withdrawn from the slot by said movement of the sheet past said slot. 10
3. Apparatus for applying granular material to sheet material which comprises means for moving said sheet in the direction of one of its surface dimensions, a structure providing a slot between surfaces generally like-extending in the direction transversely of the surface of the sheet and transversely of the movement of the sheet to provide in the slot a volume having an extent transversely of the surface of the sheet, said structure being so mounted with respect to the sheet as to provide a space between the surface of the sheet and the part of the structure forming the portion of the slot which is adjacent the sheet, said spacing of the slot structure in relation to the sheet determining with the movement of the sheet the amount of granular material withdrawn from the slot, and means for delivering to the slot granular material to replace that withdrawn from the slot by said movement of the sheet past said slot. 15
4. Apparatus for applying granular material to sheet material which comprises means for moving the sheet with its surface in a horizontal plane and in the direction of one of its surface dimensions, a structure positioned above the sheet and providing surfaces extending generally transversely to said horizontal sheet and transversely to the direction of movement of the sheet to form a slot, means for feeding to said slot a predetermined amount of granular material of a given character, the part of said structure forming the lower opening of the slot being spaced from said sheet but adjacent thereto 20 to support the granular material in the slot when the sheet is not moving thereunder, said spacing of said slot forming structure from the sheet determining in consideration of the movement of the sheet in relation thereto the amount of the granular material withdrawn from the slot and the movement downwardly therethrough, the spacing of the surfaces of the slot being such as to cause said granular material as it is withdrawn through the lower opening of the slot to move downwardly toward the sheet substantially uniformly at each point in the cross-section of the slot transverse to the movement of the granular material therethrough, and means for feeding directly upon said first granular material in said slot a predetermined amount of granular material of a character contrasting thereto. 25
5. Apparatus for applying granular material to sheet material which comprises means for moving the sheet in the plane of its extent, a slot forming structure providing surfaces extending generally parallel to each other in planes transversely of the plane of the sheet and transversely of the movement thereof, said surfaces being so spaced apart and being of such dimension transversely of the plane of the sheet as to form the slot with a substantial volume extending in said direction transversely of the sheet, means providing a plurality of quantities of granular materials, the granular material of some of said quantities contrasting with that of others of said quantities, means for delivering into said slot a predetermined amount of granular material from one of said quantities, means for delivering separate from but consecutive to and in contact with said granular material in the slot contrasting granular material from another of said quantities, and means acting concomitantly with said delivery means for cutting off delivery of said first granular material into the slot before starting delivery of said contrasting granular material into the slot, said slot forming structure being so positioned in relation to said sheet that the granular material is prevented from discharging from the slot when the sheet is not in motion but is withdrawn from the slot and immediately deposited on said sheet upon movement of the sheet relative to the slot, said structure being so spaced from the sheet that the rate of withdrawal of the granular material is determined by the rate of movement of said sheet and said spacing of said structure. 30
6. Apparatus for applying granular material to sheet material which comprises a structure providing walls forming a slot, said slot having the dimension thereof in the direction between the openings thereof substantially greater than the spacing of the walls forming the slot so as to provide a substantial volume within the slot in the direction of said dimension, said slot having one opening thereof adjacent the surface of the sheet of material, means for causing relative movement transversely of said dimension of the slot between the surface of the sheet and said opening of the 35 40 45 50 55 60 65 70 75

slot, means for causing relative movement between the other opening of the slot and separate consecutively arranged quantities of granular material so as successively to bring said other opening into register with said separate quantities separately to receive said separate quantities consecutively into said slot, said consecutive quantities of granular material being of contrasting character, said slot forming structure being so spaced from said sheet that in consideration of the rate of movement of the sheet relative to the opening of the slot the rate of withdrawal of the granular material from the slot is determined, said means for successively bringing said slot into register with the contrasting quantities of granular material being so arranged and actuated in relation to the means for causing relative movement between the sheet and the slot that the amount of each granular material delivered into the slot and withdrawn therefrom to be laid upon the sheet is predetermined.

7. Apparatus for feeding granular material comprising a structure providing a slot formed with the slot forming faces thereof having a substantial extent transverse to the opening cross-section of the slot to provide in the slot a substantial volume with respect to said cross section, means for delivering a mass of granular material of given character to the slot through one opening thereof, means for cutting off delivery of said granular material into said slot, means for causing said material to move through said slot, the spacing of said faces of the slot being so limited with respect to the grain size of the granular material as to cause said granular material to fill out said cross section of the slot and to move substantially uniformly at each point in the cross-section of the slot so as to maintain substantially a defined surface upon said mass of the granular material as it moves through the slot, whereby at each point in the movement a defined space is formed between said surface of the granular material and said opening of the slot, means for delivering contrasting granular material into said slot through said opening of the slot to fill out said cross section thereof and contiguous to said moving mass of granular material, means for cutting off delivery of said contrasting granular material into said slot, and means for actuating said means for cutting off each granular material in a predetermined relation to said means for causing said materials to move through said slot to effect said cut-off when a predetermined space is formed between said moving surface and said opening of said slot and so as to effect cut-off of said first granular material before starting of delivery of said contrasting material.

8. Apparatus for feeding granular material which comprises a slot forming structure, means providing compartments in adjacent consecutive arrangement to contain granular material, each of said compartments having an opening therein for discharge therefrom of the granular material, and means for effecting relative movement between the slot structure and said compartment means so as to cause successive registration of one opening of said slot with consecutive compartment openings to deliver the granular materials into said slot in consecutive order, said compartment means being so constructed and arranged with respect to said slot structure and said opening of said slot that during said relative movement between successive registrations one compartment opening is substantially completely

closed by a portion of said slot structure before uncovering of the consecutive compartment opening is started so as to effect delivery into said slot of said granular materials in said consecutive order unmixed with but in contact with the preceding granular material in said slot, said slot being so formed in said structure as substantially to maintain the granular materials unmixed and in said consecutive order in said slot.

9. Apparatus for feeding granular material which comprises a slot forming structure, means providing compartments in adjacent consecutive arrangement to contain granular material, each of said compartments having an opening therein for discharge therefrom of the granular material, and means for effecting relative movement between the slot structure and said compartment means so as to cause successive registration of one opening of said slot with consecutive compartment openings to deliver the granular materials into the slot in consecutive order for feed therethrough, said means for effecting relative movement between said slot structure and said compartment means being arranged to effect said movement from a position of register of the slot with one compartment opening to that of register with a consecutive compartment opening in the interval during which feeding movement of a predetermined amount of the granular material in the slot takes place, said compartment means being constructed with a part arranged with respect to said slot forming structure to uncover in said relative movement said opening of the slot to deliver the granular material from said one compartment to effect complete filling of the slot and subsequently substantially completely to cover said slot opening before uncovering of said opening of the slot to effect delivery of the granular material from the succeeding compartment in contact with said first granular material is started, whereby said granular materials in said slot are contiguous but unmixed and are of predetermined amounts.

10. Apparatus for feeding granular material which comprises a slot forming structure, means providing compartments in adjacent consecutive arrangement to contain granular material, each of said compartments having an opening therein for discharge therefrom of the granular material, and means for moving said compartment means so as to cause the openings of the consecutive compartments successively to register with one opening of the slot, said compartment means being constructed with a part arranged to cover said opening of said slot as said compartment means is moved substantially completely to close said slot opening before uncovering of the consecutive compartment opening is started so that delivery is effected into said slot of separate masses of granular materials in consecutive order unmixed with but in contact with the preceding granular material in said slot, said slot being so formed in said structure as to maintain said masses in said consecutive order and contiguous to each other but substantially unmixed as said granular material feeds therethrough.

11. Apparatus for feeding granular material comprising a slot forming structure, said slot having the dimension thereof in the direction between the openings thereof of such substantial amount as to provide a substantial volume within the slot in the direction of said dimension, means providing a plurality of compartments each containing granular material, the granular material in some compartments being of contrasting char-

- acter to that of other compartments, each of said compartments having an outlet for discharge of the granular material therefrom, said compartment means being so constructed that the outlets of the compartments containing contrasting granular material are adjacently and consecutively arranged, means for moving said slot structure to cause one opening of said slot successively to move into register with said consecutive openings to cause said slot through said opening thereof separately to receive from the compartments separate but consecutive and contiguous masses of contrasting granular material, and means acting concomitantly with said slot structure as it moves for closing the outlet opening of one compartment before uncovering the opening of a consecutive compartment to effect delivery of one mass separate and unmixed with the consecutive mass.
12. Apparatus for feeding granular material comprising a slot forming structure, said slot having the dimension thereof in the direction between the openings thereof of such substantial amount as to provide a substantial volume within the slot in the direction of said dimension, means providing a plurality of compartments each containing granular material, the granular material in some compartments being of contrasting character to that of other compartments, each of said compartments having an outlet for discharge of the granular material therefrom, said compartment means being so constructed that the outlets of the compartments containing contrasting granular material are adjacently and consecutively arranged, means for moving said slot structure to cause one opening of said slot successively to move into register with said consecutive openings to cause said slot through said opening thereof separately to receive from the compartments separate but consecutive and contiguous masses of contrasting granular material, means for supporting a web of material with its surface adjacent the other opening of the slot and so that as the slot structure is moved with respect to the compartments said other opening of the slot structure moves over the surface of the web and the granular material is caused to be withdrawn from the slot, the consecutive contrasting masses of the granular material being laid consecutively and contiguously upon the web.
13. Apparatus for feeding granular material comprising a slot forming structure, said slot having the dimension thereof in the direction between the openings thereof of such substantial amount as to provide a substantial volume within the slot in the direction of said dimension, means providing a plurality of compartments each containing granular material, the granular material in some compartments being of contrasting character to that of other compartments, each of said compartments having an outlet for discharge of the granular material therefrom, said compartment means being so constructed that the outlets of the compartments containing contrasting granular material are adjacently and consecutively arranged, means for moving said slot structure to cause one opening of said slot successively to move into register with said consecutive openings to cause said slot through said opening thereof separately to receive from the compartments separate but consecutive and contiguous masses of contrasting granular material, means for supporting a web of material with its surface adjacent the other opening of the slot and so that as the slot structure is moved with respect to the compartments said other opening of the slot structure moves over the surface of the web and the granular material is caused to be withdrawn from the slot, the consecutive contrasting masses of the granular material being laid consecutively and contiguously upon the web.

opening of the slot and so that as the slot structure is moved with respect to the compartments said other opening of the slot structure moves over the surface of the web and the granular material is caused to be withdrawn from the slot, the consecutive contrasting masses of the granular material being laid consecutively and contiguously upon the web, and means for moving said web relative to said compartment means.

14. Apparatus for feeding granular material comprising a slot forming structure, said slot having the dimension thereof in the direction between the openings thereof of such substantial amount as to provide a substantial volume within the slot in the direction of said dimension, means providing a plurality of compartments each containing granular material, the granular material in some compartments being of contrasting character to that of other compartments, each of said compartments having an outlet for discharge of the granular material therefrom, said compartment means being so constructed that the outlets of the compartments containing contrasting granular material are adjacently and consecutively arranged, means for moving said slot structure to cause one opening of said slot successively to move into register with said consecutive openings to cause said slot through said opening thereof separately to receive from the compartments separate but consecutive and contiguous masses of contrasting granular material, means for supporting a web of material with its surface adjacent the other opening of the slot and so that as the slot structure is moved with respect to the compartments said other opening of the slot structure moves over the surface of the web and the granular material is caused to be withdrawn from the slot, the consecutive contrasting masses of the granular material being laid consecutively and contiguously upon the web, means for moving said web relative to said compartment means, and means for effecting return movement of the slot structure in the reverse order with respect to said compartment openings.

15. In a machine for feeding granular material, a container for the granular material, said container being divided into compartments by upwardly extending walls, said container having the bottom wall thereof perforated with openings respectively associated with a compartment and providing for discharge from said compartments of the granular material contained therein, a carriage constructed with a slot having the opening cross-section thereof in a plane transverse to said upwardly extending walls, said slot having an extent transverse to said cross-section of the slot sufficient to provide a substantial volume within the slot, said carriage being arranged for movement thereof beneath said container in a direction to move the upper opening of said slot successively into register with the openings of said compartments, a web arranged with a stretch thereof beneath said carriage, means for moving said stretch of said web in the general direction of the line of motion of said carriage, said openings of said compartments being so proportioned and arranged with respect to said cross section of the slot as separately to discharge into said slot separate amounts of granular material from the successive compartments.

16. In a machine for feeding granular material, a container for the granular material, said container being divided into compartments by

upwardly extending walls, said container having the bottom wall thereof perforated with openings respectively associated with a compartment and providing for discharge from said compartments 5 of the granular material contained therein, a carriage constructed with a slot having the opening cross-section thereof in a plane transverse to said upwardly extending walls, said slot having an extent transverse to said cross-section of the 10 slot sufficient to provide a substantial volume within the slot, said carriage being arranged for reciprocation thereof beneath said container in a direction to move the upper opening of said slot successively in a given order into register with 15 the openings of said compartments, whereby granular material may flow from said compartments into said slot, a web arranged with a stretch thereof beneath the carriage and generally parallel to the line of motion of said carriage, means for moving said stretch of said web generally parallel to and in the direction of the line of motion of said carriage, said carriage being so positioned with respect to said stretch of said web as to provide a space between said web and the 20 structure of the carriage forming the lower opening of the slot but with said opening adjacent to said stretch of the web to prevent flow of the granular material through the slot when said carriage is not in motion with respect to said web, 25 said space being such that upon relative movement of said web and said carriage the granular material is withdrawn from the slot and is spread upon the web with a depth determined by said spacing and for a distance along said web determined by the amount of granular material within the slot. 30

17. In a machine for applying granular material to sheet material, a container for the granular material, said container being divided into compartments by upwardly extending walls, said container having the bottom wall thereof perforated with openings respectively associated with a compartment and providing for discharge from said compartments of the granular material contained therein, a carriage constructed with a slot having the opening cross-section thereof substantially in the horizontal plane, said slot having a vertical extent transverse to said cross-section of the slot sufficient to provide a substantial volume within the slot, said carriage being arranged for substantially horizontal reciprocation thereof beneath said container in a direction to move the upper opening of said slot successively into register with the openings of said compartments in a given order and then in reverse order, the 40 openings from said compartments having an area for passage therethrough of the granular material greater than the upper opening of said slot whereby granular material may readily flow from said compartments into said slot, an endless web arranged with a stretch thereof generally horizontally beneath said carriage, said carriage being so positioned with respect to said stretch of said web as to provide a space between said web and the structure of the carriage forming the 45 lower opening of the slot but with said opening adjacent to said stretch of the web to prevent flow of the granular material through the slot when said carriage is not in motion with respect to said web, said space being such that upon relative movement of said web and said carriage the granular material is withdrawn from the slot and is spread upon the web with a depth determined by said spacing and for a distance along 50 said web determined by the amount of granular 55

material within the slot, and means for moving said stretch of said web in said generally horizontal direction to carry said granular material deposited thereon and by the return movement of the web to discharge said granular material therefrom upon the sheet of material. 5

18. Apparatus according to claim 17 which comprises means for moving the sheet past the point of discharge of the granular material from said web in such relation to said movement of the carriage that said amount of granular material withdrawn from the slot is deposited upon and is spread over a predetermined length of the sheet in the direction of its motion. 10

19. In apparatus for feeding granular material, 15 a container for the granular material divided into compartments and having openings respectively associated with the compartments providing for discharge from said compartments of the granular material contained therein, a carriage 20 constructed with a slot having an extent transverse to the opening cross-section of the slot sufficient to provide a substantial volume within the slot, said carriage being arranged for reciprocation thereof with respect to said container in a 25 direction to move one opening of said slot successively into register with the openings of said compartments, means for moving a web past the other opening of said slot in the direction generally parallel to the line of reciprocation of the 30 carriage, and means for compensating for the difference in the relative movement of the carriage and the web when movement of the carriage is in the same direction as the motion of the web as compared with movement of the carriage in 35 the reverse direction so as to adjust the amounts of granular material withdrawn from the slot through said other opening by said relative movement of the slot and the web during said two motions of the reciprocation of the carriage. 40

20. Apparatus according to claim 19 in which the means for moving the carriage comprises a cam and mechanism moved thereby and connected to the carriage, said cam having the portion producing motion in the direction opposite 45 to the motion of the web formed to act through a less angle of rotation of the cam than that portion thereof which produces motion of the carriage in the direction of the motion of the web. 50

21. Apparatus according to claim 19 in which the means for moving the carriage comprises a cam and mechanism moved thereby and connected to the carriage, and means for adjusting at will the relative movement of said web with 55 respect to the rotation of the cam. 55

22. Apparatus according to claim 19 which comprises means for delivering to a sheet of material the granular material deposited on said web, means for moving said sheet in the plane of its extent past said point of delivery, and means for adjusting the movement of said sheet relative to the movement of said web to deposit said granular material upon a predetermined length of said sheet. 60

23. Apparatus according to claim 19 in which each of said compartments has the dimension of the opening thereof in the direction of the motion of the carriage of a width greater than the width of the slot opening in said direction, where- 70 by when said slot is in register with a compartment opening the granular material may freely flow into the space within the slot, the portions of the wall of the container between said compartment openings being of such width with re- 75

spect to the width of the slot opening as to cut off flow of the material from one compartment before effecting opening of the slot under the succeeding opening of the compartment.

5 24. In a mechanism for feeding granular material, a slot forming structure, a web having the surface of its extent adjacent one opening of said slot, means for effecting relative movement between said slot structure and said web to move 10 said opening over the surface of the web in a given direction and to effect return movement of said opening over said web surface, and means for effecting a different relative movement in one direction than in the other but in a predetermined 15 relation to said relative movement in the other direction.

25. In a mechanism for feeding granular material, a slot forming structure, a web having the surface of its extent adjacent one opening of said slot, means for moving said web in the direction of a dimension of its extent, and means for effecting in the general direction of said dimension of the web reciprocating movement of said slot structure with a different movement in one 25 direction than in the other to move said opening of said slot over the surface of the web in a predetermined relation to the movement of said web.

26. In a mechanism for feeding granular material, a slot forming structure, a web having the surface of its extent adjacent one opening of said slot, means for moving said web in the direction of a dimension of its extent, means for effecting reciprocating movement of said slot structure to move said opening of said slot over the 35 face of said web, and means for effecting the movement of the slot structure in one direction of the reciprocation at a rate which is greater than but in a predetermined relation to the rate of movement of the slot structure in the other 40 direction.

27. The process of applying comminuted material to a web which comprises feeding successively to the surface of the web separate masses of the material of contrasting character, causing each of said masses while being fed toward the web to flow in a path of predetermined cross section so as to fill said cross section of said path, completing the feed of one of said masses into said path before starting the feeding of a contrasting mass into said path to prevent mixture of said masses as they are fed into said path, and during said flow in said path maintaining said masses separate and substantially unmixed but contiguous and consecutive and with a defined surface of contact therebetween so as to lay said masses successively in said contiguous and unmixed relation upon said web.

28. Process of applying granular material to a web which comprises moving toward the web a mass of granular material while confining said mass to move past a given point in a path of predetermined cross-section, feeding toward said web a mass of granular material of contrasting character and causing said contrasting mass to move in said path past said point and consecutive to and contiguous to but substantially separate from said first mass of granular material, maintaining the contiguity of said separate masses throughout said movement in said path, causing the feeding of said contrasting mass to cease when the line of contiguity has moved a predetermined distance in said path from said predetermined point, and causing said masses to be laid upon the web in said consecutive and contiguous arrangement.

29. In a mechanism for feeding granular material, a slot forming structure, a web having the surface thereof adjacent one opening of the slot, means for moving said web in the direction of a surface dimension thereof, means for effecting movement of said slot structure to move said opening thereof over said surface of the web in a direction generally like extending with the movement of said web and for effecting return movement thereof over said surface in a direction generally opposite to said movement of the web, and means for effecting the movement of said structure in one direction at a different rate than in the other direction. 5 10

30. Process of feeding flowable and miscible comminuted material which comprises causing to flow into and through a defined space a succession of contrasting masses of said material so as to fill said space and to flow therethrough with each mass contiguous to but separate from and substantially unmixed with the preceding mass of contrasting character and to be discharged from said space, determining the amount of each mass of said material so flowing through said space by cutting off flow of said material into 20 said space when the line of contact of said masses in said space has moved to a point in said space which is at a predetermined distance from the point at which said material flows into said space, and varying the amount of a given mass 25 flowing through said space by varying the relation of the rate of discharge of said material from said space to the interval of time between the starting of inflow of said given mass into said space and stoppage of said flow of said mass into 30 said space. 35

31. Process of feeding flowable and miscible comminuted material which comprises causing to flow in a path of predetermined cross-section a succession of contrasting masses of said material, causing said masses to fill the cross-section of said path and to flow in said path with each mass contiguous to but substantially unmixed with a preceding mass of contrasting character so as to provide a surface of contact between said masses, and metering the amount of a mass of a given material as it flows in said path by cutting off inflow of said material into said path when said surface of contact between said mass and a preceding mass becomes spaced 40 45 from said point of inflow a predetermined distance. 50

32. Apparatus for feeding comminuted material which comprises a structure extending about and defining a space, means for feeding the comminuted material into said space and to cause movement therethrough so as to fill out the cross section of said space transverse to said movement while being confined therein, means for feeding a comminuted material of a character contrasting to that of said first material contiguous to and consecutive to the feed of said first material and so as to fill out said cross section of said space while confined therein, means for maintaining movement of said materials in said contiguous relation through said space, and means acting concomitantly with said feeding means for cutting off feed of one granular material into said space before starting feeding of a contrasting granular material into said space, whereby mixture of said materials as they are fed into said space is prevented, said space being formed in said structure with said cross section thereof so restricted as substantially to maintain upon each mass of material moving therethrough 55 60 65 70 75

- a defined surface transverse to the movement of the mass to prevent mixture of said contiguous contrasting materials therein as said materials move through said space.
- 5 33. Apparatus for applying granular material to a web which comprises a structure formed with walls extending about a space and providing separated inlet and outlet openings for said space, said structure being positioned so that said outlet opening of said space is adjacent the surface of the web, means for causing relative movement of said outlet opening and said web in the direction generally like-extending with the surface of the web to effect withdrawal of the granular material from said space, means for causing relative movement between said inlet opening of said space and separate consecutively arranged quantities of granular material successively to bring said inlet opening into register with said separate quantities to cause the granular material from said separate quantities consecutively to be delivered into said space, the spacing of said structure from the web in consideration of the rate of movement of the web relative to said outlet opening determining the rate of withdrawal of the granular material from said space, and means for actuating said second means in relation to said first means to effect movement of said inlet opening between the positions of register with two successive quantities in a predetermined interval of said relative movement between said web and said outlet opening so that the amount of each granular material delivered into the space and withdrawn therefrom to be laid upon the web is predetermined. 15
- 10 34. Apparatus for feeding granular material from said separate quantities consecutively to be delivered into said space, and means for covering said inlet opening of said space during such part of said relative movement from register with one quantity to register with a consecutive quantity as will prevent delivery of granular material from a succeeding quantity into said space before completion of delivery of the granular material from the preceding quantity. 20
- 15 35. Apparatus for feeding granular material which comprises a slot forming structure, means providing compartments in adjacent consecutive arrangement to contain granular material, each of said compartments having an opening therefor in for discharge therefrom of the granular material, and means for effecting relative movement between the slot structure and said compartment means so as to cause successive registration of one opening of said slot with consecutive compartment openings to deliver the granular materials into said slot in consecutive order for feed therethrough, said openings being spaced apart by intervening walls of such width between consecutive openings and so arranged in relation to said opening of said slot that in said relative movement between the slot structure and said compartment opening said slot opening is substantially completely closed before effecting opening of the slot to a consecutive compartment opening. 25
- 20 36. In apparatus for feeding granular material means providing separate consecutively arranged quantities of the granular material, a structure formed with walls extending about a space providing separate inlet and outlet openings for said space, means for producing the motion of reciprocation of said structure to cause said inlet opening of said space successively to move into register with said separate consecutively arranged quantities of granular material, means to cause the granular material from said separate quantities consecutively to be delivered into said space, means for moving a web past the outlet opening of said space in the direction generally like-extending with the line of motion of said structure, means for causing the granular material in said space to be discharged therefrom through said outlet opening upon said web, means for adjusting the difference between the relative movement of said structure and said web when said structure is moved in the same direction as the web and the relative movement of said structure and said web when said structure is moved in the reverse direction so as to adjust the amounts of granular material discharged from the space upon the web during said two motions of said structure. 30
- 25 37. Apparatus for applying granular material to a web which comprises a structure formed with walls extending about a space and providing separate inlet and outlet openings for said space, said structure being positioned so that said outlet opening of said space is adjacent to but spaced from the surface of the web, means for causing relative movement of said outlet opening and said web in the direction generally like-extending with the surface of the web to effect withdrawal of the granular material from said space, means for causing relative movement between said inlet opening of said space and separate consecutively arranged quantities of granular material successively to bring said inlet opening into register with said separate quantities to cause the granular material from said separate quantities consecutively to be delivered into said space, the spacing of said structure from the web in consideration of the rate of movement of the web relative to said outlet opening determining the rate of withdrawal of the granular material from said space, and means for actuating said second means in relation to said first means to effect movement of said inlet opening between the positions of register with two successive quantities in a predetermined interval of said relative movement between said web and said outlet opening so that the amount of each granular material delivered into the space and withdrawn therefrom to be laid upon the web is predetermined. 35
- 30 38. Apparatus for applying granular material to a web which comprises a structure formed with walls extending about a space and providing separate inlet and outlet openings for said space, said structure being positioned so that said outlet opening of said space is adjacent to but spaced from the surface of the web, means for causing relative movement of said outlet opening and said web in the direction generally like-extending with the surface of the web to effect withdrawal of the granular material from said space, means for causing relative movement between said inlet opening of said space and separate consecutively arranged quantities of granular material successively to bring said inlet opening into register with said separate quantities to cause the granular material from said separate quantities consecutively to be delivered into said space, the spacing of said structure from the web in consideration of the rate of movement of the web relative to said outlet opening determining the rate of withdrawal of the granular material from said space, and means for actuating said second means in relation to said first means to effect movement of said inlet opening between the positions of register with two successive quantities in a predetermined interval of said relative movement between said web and said outlet opening so that the amount of each granular material delivered into the space and withdrawn therefrom to be laid upon the web is predetermined. 40
- 35 39. Apparatus for applying granular material to a web which comprises a structure formed with walls extending about a space and providing separate inlet and outlet openings for said space, said structure being positioned so that said outlet opening of said space is adjacent to but spaced from the surface of the web, means for causing relative movement of said outlet opening and said web in the direction generally like-extending with the surface of the web to effect withdrawal of the granular material from said space, means for causing relative movement between said inlet opening of said space and separate consecutively arranged quantities of granular material successively to bring said inlet opening into register with said separate quantities to cause the granular material from said separate quantities consecutively to be delivered into said space, the spacing of said structure from the web in consideration of the rate of movement of the web relative to said outlet opening determining the rate of withdrawal of the granular material from said space, and means for actuating said second means in relation to said first means to effect movement of said inlet opening between the positions of register with two successive quantities in a predetermined interval of said relative movement between said web and said outlet opening so that the amount of each granular material delivered into the space and withdrawn therefrom to be laid upon the web is predetermined. 45
- 40 40. Apparatus for applying granular material to a web which comprises a structure formed with walls extending about a space and providing separate inlet and outlet openings for said space, said structure being positioned so that said outlet opening of said space is adjacent to but spaced from the surface of the web, means for causing relative movement of said outlet opening and said web in the direction generally like-extending with the surface of the web to effect withdrawal of the granular material from said space, means for causing relative movement between said inlet opening of said space and separate consecutively arranged quantities of granular material successively to bring said inlet opening into register with said separate quantities to cause the granular material from said separate quantities consecutively to be delivered into said space, the spacing of said structure from the web in consideration of the rate of movement of the web relative to said outlet opening determining the rate of withdrawal of the granular material from said space, and means for actuating said second means in relation to said first means to effect movement of said inlet opening between the positions of register with two successive quantities in a predetermined interval of said relative movement between said web and said outlet opening so that the amount of each granular material delivered into the space and withdrawn therefrom to be laid upon the web is predetermined. 50

CERTIFICATE OF CORRECTION.

Patent No. 2,157,944.

May 9, 1939.

ALFRED B. WALTON.

It is hereby certified that error appears in the printed specification of the above numbered patent requiring correction as follows: Page 1, first column, line 32, after "felt" insert the word granular; and second column, line 36, for "mases" read masses; page 3, second column, line 10, for "of" read or; page 4, second column, line 14, for "letter" read letters; line 64, for "portion" read pattern; page 5, second column, line 19, after "previously" insert deposited; page 6, second column, line 33, for "superimpose" read superimposed; page 8, second column, line 18, for "continguous" read contiguous; line 64, for "nuts 89" read nuts 80; page 9, first column, line 70-71, for "fastended" read fastened; page 10, first column, line 33, before "upon" insert bearing; page 12, second column, line 34, for "substracted" read subtracted; and that the said Letters Patent should be read with this correction therein that the same may conform to the record of the case in the Patent Office.

Signed and sealed this 27th day of June, A. D. 1939.

Henry Van Arsdale

(Seal)

Acting Commissioner of Patents.
